Paisner LLP(57) **ABSTRACT**

A refrigerator includes an evaporator, a defrost heater, a temperature sensor to detect a temperature associated with the evaporator, and controller to control the defrost heater. In response to a defrosting operation start time point arriving, the controller is configured to perform a defrost operation mode including a pre-defrost cooling mode, a heater operation mode, and a post-defrost cooling mode, perform a pulse operation mode in which the defrost heater is repeatedly turned on and off based on the heater operation mode, and change a magnitude of cooling power supplied in the post-defrost cooling mode based on an ON period of the defrost heater or a temperature of a cooling compartment in the pulse operation mode.

REFRIGERATOR

CROSS-REFERENCE TO RELATED APPLICATIONS

This application is the National Stage filing under 35 U.S.C. of International Application No. PCT/KR2021/005052, filed Apr. 21, 2021, which claims the benefit of earlier filing date and right of priority to Korean Application No. 10-2020-0054352, filed on May 7, 2020, Korean Application No. 10-2020-0054353, filed on May 7, 2020, the contents of which are all hereby incorporated by reference herein in their entirety.

BACKGROUND

Field of the Disclosure

The present disclosure relates to a refrigerator, and more particularly, to a refrigerator capable of improving defrosting efficiency, improving power consumption, and efficiently supplying cooling power after defrosting.

Background

For long-term storage of food in a refrigerator, a refrigerator temperature is reduced using a compressor and an evaporator. For example, a freezer compartment in the refrigerator is maintained at a temperature of approximately -18° C.

Meanwhile, in order to improve refrigerator performance, it is desirable to remove frost which may be on the evaporator when the evaporator operates.

Korean Patent Application Laid-Open No. 10-2001-0026176 (hereinafter, referred to as Document 1) relates to a method of controlling a defrost heater of a refrigerator, in which the defrost heater is turned on when a certain time for defrosting arrives, and turned off after a certain period of time for defrosting lapses.

However, according to Document 1, since the ON time and the OFF time of the defrost heater are based on a certain time or a predetermined time, defrosting is not performed according to the actual amount of frost on an evaporator. That is, when the amount of frost is large, defrosting is not performed properly, or when the amount of frost is small, unnecessary defrosting is performed, thereby unnecessarily consuming power.

U.S. Pat. No. 6,694,754 (hereinafter, referred to as Document 2) relates to a refrigerator having a pulse-based defrost heater, and discloses that the On and off time of a defrost heater is determined based on time.

According to Document 2, since the ON time and the OFF time of the defrost heater are determined based on time, defrosting is not performed according to the actual amount of frost on an evaporator. That is, when the amount of frost is large, defrosting is not performed properly, or when the amount of frost is small, unnecessary defrosting is performed, thereby unnecessarily consuming power.

Korean Patent Application Laid-Open No. 10-2016-0053502 (hereinafter, referred to as Document 3) relates to a defrosting device, a refrigerator having the same, and a control method of the defrosting device, in which the ON and OFF time of a defrost heater determined based on time or time and temperature.

According to Document 3, since the ON time and the OFF time of the defrost heater are determined based on time or time and temperature, defrosting is not performed according

2

to the actual amount of frost on an evaporator. That is, when the amount of frost is large, defrosting is not performed properly, or when the amount of frost is small, unnecessary defrosting is performed, thereby unnecessarily consuming power.

SUMMARY

An aspect of the present disclosure to provide a refrigerator capable of improving defrosting efficiency, improving power consumption, and efficiently supplying cooling power after defrosting.

In one aspect, a refrigerator includes an evaporator configured to perform heat exchange, a defrost heater configured to operate to remove frost from the evaporator, a temperature sensor configured to detect a temperature associated with the evaporator, and controller configured to control the defrost heater, wherein, in response to a defrosting operation start time point arriving, the controller is configured to perform a defrost operation mode including a pre-defrost cooling mode, a heater operation mode, and a post-defrost cooling mode, perform a pulse operation mode in which the defrost heater is repeatedly turned on and off based on the heater operation mode, and change a magnitude of cooling power supplied in the post-defrost cooling mode based on an ON period of the defrost heater or a temperature of a cooling compartment in the pulse operation mode.

The controller may control the defrost heater to perform a continuous operation mode in which the defrost heater is continuously turned on and a pulse operation mode based on the heater operation mode.

In response to the ON period of the defrost heater or the temperature of the cooling compartment in the pulse operation mode being less than or equal to a set value, the controller may be configured to change the magnitude of cooling power supplied in the post-defrost cooling mode based on the ON period of the defrost heater or the temperature of the cooling compartment, and in response to the ON period of the defrost heater or the temperature of the cooling compartment in the pulse operation mode exceeding the set value, the controller may be configured to supply maximum cooling power in the post-defrost cooling mode.

In response to the temperature of the cooling compartment being equal to or lower than a cooling compartment reference temperature, the controller may be configured to change a magnitude of cooling power supplied in the post-defrost cooling mode based on the ON period of the defrost heater or the temperature of the cooling compartment, and in response to the temperature of the cooling compartment exceeding the cooling compartment reference temperature, the controller may be configured to supply maximum cooling power in the post-defrost cooling mode.

In response to a temperature of a refrigerating compartment being equal to or lower than a refrigerating compartment reference temperature and a temperature of a freezer compartment is equal to or lower than a freezer compartment reference temperature, the controller may be configured to change a magnitude of cooling power supplied in the post-defrost cooling mode based on the ON period of the defrost heater or the temperature of the cooling compartment.

In response to the temperature of the refrigerating compartment exceeding the refrigerating compartment reference temperature and the temperature of the freezer compartment exceeding the freezer compartment reference temperature, the controller may be configured to supply maximum cooling power in the post-defrost cooling mode.

As the ON period of the defrost heater in the pulse operation mode increases, the controller may be configured to increase the magnitude of cooling power supplied in the post-defrost cooling mode.

As the temperature of the cooling compartment, which is equal to or lower than a cooling compartment reference temperature, increases, the controller may be configured to increase the magnitude of cooling power supplied in the post-defrost cooling mode.

The controller may be configured to change a magnitude of cooling power supplied in the post-defrost cooling mode in inverse proportion to a difference between a set temperature and the temperature of the cooling compartment, after the pulse operation mode.

In response to the continuous operation mode being performed after the pulse operation mode, the controller may be configured to control the magnitude of cooling power supplied in the post-defrost cooling mode to be larger than in response to only the pulse operation mode being performed.

In response to the pulse operation mode being performed after the continuous operation mode, the controller may be configured to control the magnitude of cooling power supplied in the post-defrost cooling mode to be larger than in response to only the pulse operation mode being performed.

The controller may be configured to change the magnitude of cooling power supplied in the post-defrost cooling mode in proportion to a door opening period during the pulse operation mode.

In response to the defrosting operation start time point arriving while performing the normal cooling operation mode, the controller may be configured to perform the defrost operation mode including the pre-defrost cooling mode, the heater operation mode, and the post-defrost cooling mode, and may be configured to perform the continuous operation mode of the defrost heater and the pulse operation mode in which the defrost heater is repeatedly turned on and off based on the heater operation mode.

The controller may control the defrost heater to be continuously turned on based on the continuous operation mode, and in response to a change rate of a temperature associated with the evaporator detected by the temperature sensor being equal to or greater than a first reference value in the ON state of the defrost heater, the controller may perform the pulse operation mode and controls the defrost heater to be turned off, and in response to the change rate of the temperature associated with the evaporator being less than or equal to a second reference value less than the first reference value in the OFF state of the defrost heater during the pulse operation mode, the controller may control the defrost heater to be turned on.

The controller may control the defrost heater to be continuously turned on based on the continuous operation mode, and repeat On and off of the defrost heater for the change rate of the temperature associated with the evaporator to be between a first reference value and a second reference value based on the pulse operation mode.

As the number of opening times of the cooling compartment door increases, the controller may be configured to decrease a period of performing the defrost operation mode.

The controller may be configured to control a peak temperature arrival point of the evaporator in response to the continuous operation mode and the pulse operation mode being performed in the defrost operation mode to be later than a peak temperature arrival point of the evaporator in response to the defrost heater being only continuously turned on in the defrost operation mode.

The controller may be configured to control a size of a second section related to a temperature against time between a phase-change temperature and a defrost end temperature in response to the continuous operation mode and the pulse operation mode being performed in the defrosting operation mode to be greater than a size of a first section related to a temperature against time between the phase-change temperature and the defrost end temperature in response to the defrost heater being only continuously turned on in the defrost operation mode.

The controller may be configured to control an effective defrost in response to the continuous operation mode and the pulse operation mode being performed in the defrost operation mode to be greater than an effective defrost in response to the defrost heater being only continuously turned on in the defrost operation mode.

The controller may be configured to control a heater OFF time point in response to the continuous operation mode and the pulse operation mode being performed in the defrost operation mode to be later than a heater OFF time point in response to the defrost heater being only continuously turned on in the defrost operation mode.

In response to the defrosting operation start time point arriving, the controller may be configured to perform the defrost operation mode including the pre-defrost cooling mode, the heater operation mode, and the post-defrost cooling mode, and may control the defrost heater to perform the continuous operation mode in which the defrost heater is continuously turned on and perform the pulse operation mode in which the defrost heater is repeatedly turned on and off based on the heater operation mode, and in response to the cooling compartment door being opened during the continuous operation mode, the controller may be configured to turn off the defrost heater, and supply a predetermined level of cooling power in the post-defrost cooling mode.

In another aspect, a refrigerator includes: an evaporator configured to perform heat exchange; a defrost heater configured to operate to remove frost from the evaporator; a temperature sensor configured to detect a temperature associated with the evaporator; and a controller configured to control the defrost heater, wherein, in response to a defrosting operation start time point arriving, the controller is configured to perform a defrost operation mode including a pre-defrost cooling mode, a heater operation mode, and a post-defrost cooling mode, and perform a continuous operation mode in which the defrost heater is continuously turned on and a pulse operation mode in which the defrost heater is repeatedly turned on and off based on the heater operation mode, and in response to a cooling compartment door being opened during the continuous operation mode, turn off the defrost heater and supply a predetermined level of cooling power in the post-defrost cooling mode.

In response to the cooling compartment door being opened during the continuous operation mode, the controller may be configured to end the continuous operation mode, turn off the defrost heater, and supply a predetermined level of cooling power in the post-defrost cooling mode.

In response to the cooling compartment door being opened during the pulse operation mode, the controller may be configured to end the pulse operation mode, turn off the defrost heater, and supply a predetermined level of cooling power in the post-defrost cooling mode.

In another aspect, a refrigerator includes an evaporator configured to perform heat exchange, a defrost heater configured to operate to remove frost from the evaporator, a temperature sensor configured to detect a temperature asso-

ciated with the evaporator, and a controller configured to control the defrost heater, wherein, in response to a defrosting operation start time point arriving, the controller is configured to perform a defrost operation mode including a pre-defrost cooling mode, a heater operation mode, and post-defrost cooling mode, perform a continuous operation mode in which the defrost heater is continuously turned on and a pulse operation mode in which the defrost heater is repeatedly turned on and off based on the heater operation mode, and change a magnitude of cooling power supplied in the post-defrost cooling mode based on an ON period of the defrost heater or a temperature of the cooling compartment in the pulse operation mode, and in response to the temperature of the cooling compartment in a previous defrost operation not reaching a target temperature or in response to a defrost end temperature in the previous defrost operation being equal to or higher than a set temperature, the controller is configured to supply a predetermined level of cooling power in the post-defrost cooling mode.

A refrigerator according to an embodiment of the present disclosure includes an evaporator configured to perform heat exchange, a defrost heater configured to operate to remove frost from the evaporator, a temperature sensor configured to detect a temperature associated the evaporator, and controller configured to control the defrost heater, wherein, in response to a defrosting operation start time point arriving, the controller is configured to perform a defrost operation mode including a pre-defrost cooling mode, a heater operation mode, and a post-defrost cooling mode, perform a pulse operation mode in which the defrost heater is repeatedly turned on and off based on the heater operation mode, and change a magnitude of cooling power supplied in the post-defrost cooling mode based on an ON period of the defrost heater or a temperature of a cooling compartment in the pulse operation mode. Accordingly, defrosting efficiency may be improved, power consumption may be improved, and cooling power after defrosting may be efficiently supplied. In particular, since defrosting is performed according to the actual amount of frost on the evaporator, defrosting efficiency and power consumption may be improved.

Meanwhile, the controller may control the defrost heater to perform a continuous operation mode in which the defrost heater is continuously turned on and a pulse operation mode based on the heater operation mode. Accordingly, defrosting efficiency may be improved and power consumption may be improved.

Meanwhile, in response to the ON period of the defrost heater or the temperature of the cooling compartment in the pulse operation mode being less than or equal to a set value, the controller may be configured to change the magnitude of cooling power supplied in the post-defrost cooling mode based on the ON period of the defrost heater or the temperature of the cooling compartment in the pulse operation mode exceeding the set value, the controller may be configured to supply maximum cooling power in the post-defrost cooling mode. Accordingly, defrosting efficiency may be improved, power consumption may be improved, and cooling power after defrosting may be efficiently supplied.

Meanwhile, in response to the temperature of the cooling compartment being equal to or lower than a cooling compartment reference temperature, the controller may be configured to change the magnitude of cooling power supplied in the post-defrost cooling mode based on the ON period of the defrost heater or the temperature of the cooling compartment, and in response to the temperature of the cooling

compartment exceeding the cooling compartment reference temperature, the controller may be configured to supply maximum cooling power in the post-defrost cooling mode. Accordingly, defrosting efficiency may be improved, power consumption may be improved, and cooling power after defrosting may be efficiently supplied.

Meanwhile, a temperature of a refrigerating compartment is equal to or lower than a refrigerating compartment reference temperature and a temperature of a freezer compartment is equal to or lower than a freezer compartment reference temperature, the controller may be configured to change the magnitude of cooling power supplied in the post-defrost cooling mode based on the ON period of the defrost heater or the temperature of the cooling compartment. Accordingly, defrosting efficiency may be improved, power consumption may be improved, and cooling power after defrosting may be efficiently supplied.

Meanwhile, in response to the temperature of the refrigerating compartment exceeding the refrigerating compartment reference temperature and the temperature of the freezer compartment exceeding the freezer compartment reference temperature, the controller may be configured to supply maximum cooling power in the post-defrost cooling mode. Accordingly, defrosting efficiency may be improved, power consumption may be improved, and cooling power after defrosting may be efficiently supplied.

Meanwhile, as the ON period of the defrost heater in the pulse operation mode increases, the controller may be configured to increase the magnitude of cooling power supplied in the post-defrost cooling mode. Accordingly, defrosting efficiency may be improved, power consumption may be improved, and cooling power after defrosting may be efficiently supplied.

Meanwhile, as the temperature of the cooling compartment, which is equal to or lower than the cooling compartment reference temperature, increases, the controller may be configured to increase the magnitude of cooling power supplied in the post-defrost cooling mode. Accordingly, defrosting efficiency may be improved, power consumption may be improved, and cooling power after defrosting may be efficiently supplied.

Meanwhile, the controller may be configured to change a magnitude of cooling power supplied in the post-defrost cooling mode in inverse proportion to a difference between the set temperature and the temperature of the cooling compartment, after the pulse operation mode. Accordingly, defrosting efficiency may be improved, power consumption may be improved, and cooling power after defrosting may be efficiently supplied.

Meanwhile, In response to the continuous operation mode being performed after the pulse operation mode, the controller may be configured to control the magnitude of cooling power supplied in the post-defrost cooling mode to be larger than in response to only the pulse operation mode being performed. Accordingly, defrosting efficiency may be improved, power consumption may be improved, and cooling power after defrosting may be efficiently supplied.

Meanwhile, In response to the pulse operation mode being performed after the continuous operation mode, the controller may be configured to control the magnitude of cooling power supplied in the post-defrost cooling mode to be larger than in response to only the pulse operation mode being performed. Accordingly, defrosting efficiency may be improved, power consumption may be improved, and cooling power after defrosting may be efficiently supplied.

Meanwhile, the controller may be configured to change the magnitude of cooling power supplied in the post-defrost

cooling mode in proportion to a door opening period during the pulse operation mode. Accordingly, defrosting efficiency may be improved, power consumption may be improved, and cooling power after defrosting may efficiently supplied.

Meanwhile, the controller may be configured to control a peak temperature arrival point of the evaporator in response to the continuous operation mode and the pulse operation mode being performed in the defrost operation mode to be later than a peak temperature arrival point of the evaporator in response to the defrost heater being only continuously turned on in the defrost operation mode. Accordingly, defrosting efficiency may be improved and power consumption may be improved.

Meanwhile, the controller may be configured to control a size of a second section related to a temperature against time between a phase-change temperature and a defrost end temperature in response to the continuous operation mode and the pulse operation mode being performed in the defrosting operation mode to be greater than a size of a first section related to a temperature against time between the phase-change temperature and the defrost end temperature in response to the defrost heater being only continuously turned on in the defrost operation mode. Accordingly, defrosting efficiency may be improved and power consumption may be improved.

Meanwhile, the controller may be configured to control an effective defrost in response to the continuous operation mode and the pulse operation mode being performed in the defrost operation mode to be greater than an effective defrost in response to the defrost heater being only continuously turned on in the defrost operation mode. Accordingly, defrosting efficiency may be improved and power consumption may be improved.

Meanwhile, the controller may be configured to control a heater OFF time point in response to the continuous operation mode and the pulse operation mode being performed in the defrost operation mode to be later than a heater OFF time point in response to the defrost heater being only continuously turned on in the defrost operation mode. Accordingly, defrosting efficiency may be improved and power consumption may be improved.

Meanwhile, in response to the defrosting operation start time point arriving, the controller may be configured to perform the defrost operation mode including the pre-defrost cooling mode, the heater operation mode, and the post-defrost cooling mode, and may control the defrost heater to perform the continuous operation mode in which the defrost heater is continuously turned on and perform the pulse operation mode in which the defrost heater is repeatedly turned on and off based on the heater operation mode, and in response to the cooling compartment door being opened during the continuous operation mode, the controller may be configured to turn off the defrost heater, and supply a predetermined level of cooling power in the post-defrost cooling mode. Accordingly, defrosting efficiency may be improved, power consumption may be improved, and cooling power after defrosting may be efficiently supplied.

A refrigerator according to another embodiment of the present disclosure includes: an evaporator configured to perform heat exchange; a defrost heater configured to operate to remove frost from the evaporator; a temperature sensor configured to detect a temperature associated with the evaporator; and a controller configured to control the defrost heater, wherein, in response to a defrosting operation start time point arriving, the controller is configured to perform a defrost operation mode including a pre-defrost cooling mode, a heater operation mode, and a post-defrost cooling

mode, and perform a continuous operation mode in which the defrost heater is continuously turned on and a pulse operation mode in which the defrost heater is repeatedly turned on and off based on the heater operation mode, and in response to a cooling compartment door being opened during the continuous operation mode, turn off the defrost heater and supply predetermined level of cooling power in the post-defrost cooling mode. Accordingly, defrosting efficiency may be improved, power consumption may be improved, and cooling power after defrosting may be efficiently supplied. In particular, since defrosting is performed according to the actual amount of frost on the evaporator, defrosting efficiency and power consumption may be improved.

Meanwhile, in response to the cooling compartment door being opened during the continuous operation mode, the controller may be configured to end the continuous operation mode, turn off the defrost heater, and supply a predetermined level of cooling power in the post-defrost cooling mode. Accordingly, defrosting efficiency may be improved, power consumption may be improved, and cooling power after defrosting may be efficiently supplied.

Meanwhile, in response to the cooling compartment door being opened during the pulse operation mode, the controller may be configured to end the pulse operation mode, turn off the defrost heater, and supply a predetermined level of cooling power in the post-defrost cooling mode. Accordingly, defrosting efficiency may be improved, power consumption may be improved, and cooling power after defrosting may be efficiently supplied.

A refrigerator according to another embodiment of the present disclosure includes an evaporator configured to perform heat exchange, a defrost heater configured to operate to remove frost from the evaporator, a temperature sensor configured to detect a temperature associated with the evaporator, and a controller configured to control the defrost heater, wherein, in response to a defrosting operation start time point arriving, the controller is configured to perform a defrost operation mode including a pre-defrost cooling mode, a heater operation mode, and a post-defrost cooling mode, perform a continuous operation mode in which the defrost heater is continuously turned on and a pulse operation mode in which the defrost heater is repeatedly turned on and off based on the heater operation mode, and change a magnitude of cooling power supplied in the post-defrost cooling mode based on an ON period of the defrost heater or a temperature of the cooling compartment in the pulse operation mode, and in response to the temperature of the cooling compartment in a previous defrost operation not reaching a target temperature or in response to a defrost end temperature in the previous defrost operation being equal to or higher than a set temperature, the controller is configured to supply a predetermined level of cooling power in the post-defrost cooling mode. Accordingly, defrosting efficiency may be improved, power consumption may be improved, and cooling power after defrosting may be efficiently supplied.

BRIEF DESCRIPTION OF THE DRAWINGS

FIG. 1 is a perspective view illustrating a refrigerator according to an embodiment of the present disclosure;

FIG. 2 is a perspective view of the refrigerator of FIG. 1 with doors open;

FIG. 3 is a diagram schematically illustrating a configuration of the refrigerator of FIG. 1;

FIG. 4 is a block diagram schematically illustrating components of the refrigerator shown in FIG. 1;

FIG. 5A is a perspective view illustrating an example of an evaporator associated with the present disclosure;

FIG. 5B is a perspective view illustrating frost ICE on the evaporator referenced in FIG. 5A;

FIG. 6 is a flowchart illustrating a method of operating a refrigerator according to an embodiment of the present disclosure;

FIGS. 7A to 13 are diagrams referenced in the description of FIG. 6;

FIG. 14 is a flowchart illustrating a method of defrosting and cooling after defrosting according to an embodiment of the present disclosure;

FIG. 17 is a flowchart illustrating a method of defrosting and cooling after defrosting according to another embodiment of the present disclosure;

FIGS. 18A to 18E are diagrams referenced in the description of FIG. 17;

FIG. 19 is a flowchart illustrating a method of defrosting and cooling after defrosting according to another embodiment of the present disclosure; and

FIG. 20 is a flowchart illustrating a method of defrosting and cooling after defrosting according to another embodiment of the present disclosure.

DETAILED DESCRIPTION

Hereinafter, the present disclosure will be described in further detail with reference to the accompanying drawings.

The suffixes "module" and "unit" in elements used in the description below are given in consideration of ease in preparation of the specification and do not have specific meanings or functions. Therefore, the suffixes "module" and "unit" may be used interchangeably.

FIG. 1 is a perspective view illustrating a refrigerator according to an embodiment of the present disclosure.

Referring to the drawings, a refrigerator 100 according to an embodiment of the present disclosure forms an outer shape by a case 110 having an internal space divided into a freezer compartment and a refrigerating compartment, a freezer compartment door 120 that closes the freezer compartment, and a refrigerator door 140 that closes the refrigerating compartment.

In addition, the front surface of the freezer compartment door 120 and the refrigerating compartment door 140 are further provided with door handles 121 protruding forward, so that a user may easily grip and open the freezer compartment door 120 and the refrigerating compartment door 140.

Meanwhile, the front surface of the refrigerating compartment door 140 may be further provided with a home bar 180 which is a convenient means for allowing the user to take out a stored item such as a beverage contained therein without opening the refrigerating compartment door 140.

In addition, the front surface of the freezer compartment door 120 may be provided with a dispenser 160 which is a convenient means for allowing the user to easily take out ice or drinking water without opening the freezer compartment door 120, and a control panel 210 for controlling the driving operation of the refrigerator 100 and displaying the state of

the refrigerator 100 being operated on a screen may be further provided at an upper side of the dispenser 160.

Meanwhile, in the drawing, it is illustrated that the dispenser 160 is disposed in the front surface of the freezer compartment door 120, but it is not limited thereto, and may be disposed in the front surface of the refrigerating compartment door 140.

The control panel 210 may include an input device 220 having a plurality of buttons, and a display device 230 for displaying a control screen, an operation state, and the like.

The display device 230 displays information such as a control screen, an operation state, a temperature inside the refrigerator, and the like. For example, the display device 230 may display the set temperature of the freezer compartment and the set temperature of the refrigerating compartment.

The display device 230 may be implemented in various ways, such as a liquid crystal display (LCD), a light emitting diode (LED), an organic light emitting diode (OLED), and the like. In addition, the display device 230 may be implemented as a touch screen capable of serving as the input device 220.

The input device 220 may include a plurality of operation buttons. For example, the input device 220 may include a freezer compartment temperature setting button for setting the freezer compartment temperature, and a refrigerating compartment temperature setting button for setting the refrigerating compartment temperature. Meanwhile, the input device 220 may be implemented as a touch screen that may also function as the display device 230.

It should be understood that the refrigerator according to an embodiment of the present disclosure is not limited to a double door type shown in the drawing, but may be a one door type, a sliding door type, a curtain door type, and the like.

FIG. 2 is a perspective view of the refrigerator of FIG. 1 with doors open.

Referring to the drawing, a freezer compartment 155 is disposed inside the freezer compartment door 120, and a refrigerating compartment 157 is disposed inside the refrigerating compartment door 140.

FIG. 3 is a diagram schematically illustrating a configuration of the refrigerator of FIG. 1.

Referring to the drawing, the refrigerator 100 may include a compressor 112, a condenser 116 for condensing a refrigerant compressed by the compressor 112, a freezer compartment evaporator 122 which is supplied with the refrigerant condensed in the condenser 116 to evaporate, and is disposed in the freezer compartment, and a freezer compartment expansion valve 132 for expanding the refrigerant supplied to the freezer compartment evaporator 122.

Meanwhile, in the drawing, it is illustrated that a single evaporator is used, but it is also possible to use evaporators in the refrigerating compartment and the freezer compartment, respectively.

That is, the refrigerator 100 may further include a refrigerating compartment evaporator (not shown) disposed in a refrigerating compartment (not shown), a three-way valve (not shown) for supplying the refrigerant condensed in the condenser 116 to the refrigerating compartment evaporator (not shown) or the freezer compartment evaporator 122, and a refrigerating compartment expansion valve (not shown) for expanding the refrigerant supplied to the refrigerating compartment evaporator (not shown).

11

In addition, the refrigerator 100 may further include a gas-liquid separator (not shown) which separates the refrigerant passed through the evaporator 122 into a liquid and a gas.

In addition, the refrigerator 100 may further include a refrigerating compartment fan (not shown) and a freezer compartment fan 144 that suck cold air generated through the freezer compartment evaporator 122 and blow the sucked cold air into a refrigerating compartment (not shown) and a freezer compartment (not shown), respectively.

In addition, the refrigerator 100 may further include a compressor driver 113 for driving the compressor 112, and a refrigerating compartment fan driver (not shown) and a freezer compartment fan driver 145 for driving the refrigerating compartment fan (not shown) and the freezer compartment 144, respectively.

Meanwhile, based on the drawing, since a common evaporator 122 is used for the refrigerating compartment and the freezer compartment, in this case, a damper (not shown) may be installed between the refrigerating compartment and the freezer compartment, and a fan (not shown) may forcibly blow the cold air generated in one evaporator to be supplied to the freezer compartment and the refrigerating compartment.

FIG. 4 is a block diagram schematically illustrating components of the refrigerator shown in FIG. 1.

Referring to the drawings, the refrigerator of FIG. 4 includes a compressor 112, a machine room fan 115, the freezer compartment fan 144, a controller 310, a heater 330, a temperature sensor 320, a memory 240, and an evaporator 122. The controller 310 may be a microprocessor, a logic electrical circuit, an integrated circuit, and the like.

In addition, the refrigerator may further include a compressor driver 113, a machine room fan driver 117, a freezer compartment fan driver 145, a heater driver 332, a display device 230, and an input device 220.

The compressor 112, the machine room fan 115, and the freezer compartment fan 144 are described with reference to FIG. 2.

The input device 220 includes a plurality of operation buttons, and transmits a signal for an input freezer compartment set temperature or refrigerating compartment set temperature to the controller 310.

The display device 230 may display an operation state of the refrigerator. Meanwhile, the display device 230 is operable under the control of a display controller (not shown).

The memory 240 may store data necessary for operating the refrigerator.

For example, the memory 240 may store power consumption information for each of the plurality of power consumption devices. In addition, the memory 240 may output corresponding power consumption information to the controller 310 based on the operation of each power consumption device in the refrigerator.

The temperature sensor 320 detects a temperature in the refrigerator and transmits a signal for the detected temperature to the controller 310. Here, the temperature sensor 320 detects the refrigerating compartment temperature and the freezer compartment temperature respectively. In addition, the temperature of each chamber in the refrigerating compartment or each chamber in the freezer compartment may be detected.

In order to control an ON/OFF operation of the compressor 112, the fan 115 or 144, and the heater 330, as shown in the drawing, the controller may control the compressor driver 113, the fan driver 117 or 145, and the heater driver 332 to control the compressor 112, the fan 115 or 144, and

12

the heater 330, respectively. Here, the fan driver may be the machine room fan driver 117 or the freezer compartment fan driver 145.

For example, the controller 310 may output a corresponding speed command value signal to the compressor driver 113 or the fan driver 117 or 145, respectively.

The compressor driver 113 and the freezer compartment fan driver 145 described above are provided with a compressor motor (not shown) and a freezer compartment fan motor (not shown) respectively, and each motor (not shown) may be operated at a target rotational speed under the control of the controller 310.

Meanwhile, the machine room fan driver 117 includes a machine room fan motor (not shown), and the machine room fan motor (not shown) may be operated at a target rotational speed under the control of the controller 310.

When the motor is a three-phase motor, it may be controlled by a switching operation of an inverter (not shown) or may be controlled at a constant speed by using an AC power source. Each motor may be any one of an induction motor, a Brush less DC (BLDC) motor, a synchronous reluctance motor (synRM) motor, and the like.

Meanwhile, as described above, the controller 310 may control the overall operation of the refrigerator 100, in addition to the operation control of the compressor 112 and the fan 115 or 144.

For example, as described above, the controller 310 may control the overall operation of the refrigerant cycle based on the set temperature from the input device 220. For example, the controller 310 may further control a three-way valve (not shown), a refrigerating compartment expansion valve (not shown), and a freezer compartment expansion valve 132, in addition to the compressor driver 113, the refrigerating compartment fan driver (not shown), and the freezer compartment fan driver 145. In addition, the operation of the condenser 116 may also be controlled. In addition, the controller 310 may control the operation of the display device 230.

Meanwhile, the cold air heat-exchanged at the evaporator 122 may be supplied to the freezer compartment or the refrigerating compartment by a fan or a damper (not shown).

Meanwhile, the heater 330 may be a freezer compartment defrost heater. For example, when only one freezer compartment evaporator 122 is used in the refrigerator 100, the freezer compartment defrost heater 330 may operate to remove frost attached to the freezer compartment evaporator 122. To this end, the heater driver 332 may control the operation of the heater 330. Meanwhile, the controller 310 may control the heater driver 332.

The heater 330 may include a freezer compartment defrost heater and a refrigerating compartment defrost heater. For example, when the freezer compartment evaporator 122 and the refrigerating compartment evaporator (not shown) are separately used in the refrigerator 100, the freezer compartment defrost heater 330 may operate to remove frost attached to the freezer compartment evaporator 122, and the refrigerating compartment defrost heater (not shown) may operate to remove frost attached to the refrigerating compartment evaporator. To this end, the heater driver 332 may control the operations of the freezer compartment defrost heater 330 and the refrigerating compartment defrost heater.

FIG. 5A is a perspective view illustrating an example of an evaporator related to the present disclosure, and FIG. 5B is a perspective view illustrating frost ICE on the evaporator referenced in FIG. 5A.

13

Referring to FIG. 5A, the evaporator 122 in the refrigerator 100 may be a freezer compartment evaporator as described above with reference to FIG. 3.

A sensor mounter 400 including a temperature sensor 320 may be attached to the evaporator 122 in the refrigerator 100.

In the drawing, it is illustrated that a sensor mounter 400 is attached to an upper cooling pipe of the evaporator 122 in the refrigerator 100.

The evaporator 122 includes a cooling pipe 131 extending from one side of the accumulator 134 and a support 133 supporting the cooling pipe 131.

The cooling pipe 131 may be repeatedly bent in a zigzag manner to form multiple rows and may be filled with a refrigerant.

Meanwhile, the defrost heater 330 for defrosting may be disposed in the vicinity of the cooling pipe 131 of the evaporator 122.

In the drawing, it is illustrated that the defrost heater 330 is disposed in the vicinity of the cooling pipe 131 in a lower region of the evaporator 122.

For example, since frost ICE is usually formed from a lower region of the evaporator 122 and grows in an upward direction, preferably, the defrost heater 330 may be disposed in the vicinity of the cooling pipe 131 in the lower region of the evaporator 122.

Accordingly, as shown in the drawing, the defrost heater 330 may be disposed in a shape surrounding the cooling pipe 131 of the lower region of the evaporator 122.

Meanwhile, FIG. 5B illustrates frost ICE attached to the evaporator 122.

In the drawing, it is illustrated that frost ICE is attached to a central portion and a lower portion of the evaporator 122.

In particular, in the drawing, it is illustrated that frost ICE is formed on the defrost heater 330 to cover the defrost heater 330.

When the defrost heater 330 operates, frost ICE may be removed from the lower region of the evaporator 122 and may be gradually removed in the direction of the central region.

Meanwhile, in the present disclosure, a method for improving defrosting efficiency and power consumption when removing frost ICE, that is, defrosting, is proposed. This will be described with reference to FIG. 6 and the following drawings.

FIG. 6 is a flowchart illustrating a method of operating a refrigerator according to an embodiment of the present disclosure.

Referring to the drawings, the controller 310 of the refrigerator 100 according to an embodiment of the present disclosure determines whether a defrosting operation start time point for defrosting has arrived (S610).

For example, the controller 310 of the refrigerator 100 may determine whether a defrosting operation start time point has arrived while performing a normal cooling operation mode Pga (see for example, FIG. 8A).

The defrosting operation start time point may vary according to a defrost cycle.

For example, when the number of times of a door of the cooling compartment (the refrigerating compartment or the freezer compartment) is opened increases, the amount of cold air supplied in the normal cooling operation mode increases, and accordingly, a rate at which frost is formed on the evaporator 122 may also increase.

Accordingly, when the number of times of the door of the cooling compartment (the refrigerating compartment or the

14

freezer compartment) is opened increases, the controller 310 of the refrigerator 100 may control such that a defrost cycle is decreased.

That is, when the number of times of the door of the cooling compartment (the refrigerating compartment or the freezer compartment) is opened increases, the controller 310 of the refrigerator 100 may control the defrosting operation start time point to be decreased.

Meanwhile, when a defrosting operation start condition is satisfied, for example, in response to a defrosting operation start time point arriving, the controller 310 of the refrigerator 100 may end the normal cooling operation mode, control to perform a defrost operation mode Pdf, and control the defrost heater 330 to be continuously turned on according to a heater operation mode PddT in the defrost operation mode Pdf (S615).

Next, the controller 310 of the refrigerator 100 may control to perform a pulse operation mode in which the defrost heater 330 is repeatedly turned on and off by a heater pulse after the defrost heater 330 is continuously turned on (S620).

For example, when the defrost operation start condition is satisfied, the controller 310 of the refrigerator 100 may control to perform the defrost operation mode Pdf including a pre-defrost cooling mode Pbd, a heater operation mode PddT, and a post-defrost cooling mode pbf.

Also, based on the heater operation mode PddT, according to the defrost operation mode pdf, the controller may control to perform a continuous operation mode Pona in which the defrost heater 330 is continuously turned on and a pulse operation mode Ponb in which the defrost heater 330 is repeatedly turned on and off.

Meanwhile, the controller 310 controls the defrost heater 330 to be continuously turned on based on the continuous operation mode Pona, and in the ON state of the defrost heater 330, when a change rate of the temperature associated with the evaporator 122 detected by the temperature sensor 320 is equal to or greater than a first reference value ref1, the controller 310 may enter the pulse operation mode Ponb to control the defrost heater 330 to be turned off. Accordingly, defrosting efficiency and power consumption may be improved.

Meanwhile, the controller 310 of the refrigerator 100 may control the defrost heater 330 to be turned on and off according to a change rate of the temperature detected by the temperature sensor 320 when the pulse operation mode Ponb is performed.

For example, when performing the pulse operation mode Ponb, if the change rate of the temperature detected by the temperature sensor 320 is equal to or greater than the first reference value ref1, the controller 310 of the refrigerator 100 may control the defrost heater 330 to be turned off, and if the change rate of the temperature detected by the temperature sensor 320 is less than or equal to a second reference value ref2, which is smaller than the first reference value ref1, the controller 310 may control the defrost heater 330 to be turned on. Accordingly, since defrosting may be performed based on a change rate ΔT of the temperature, defrosting efficiency and power consumption may be improved.

Next, the controller 310 of the refrigerator 100 determines whether a pulse operation mode end time point has arrived (S630), and if pulse operation mode end time point has arrived, the controller 310 turns off the defrost heater 330 (S640).

For example, the pulse operation mode end time point may be a time point at which the temperature detected by the temperature sensor 320 falls below a phase-change temperature Trf1.

As another example, the pulse operation mode end time point may be an end time point of the defrosting operation or an end time point of the heater operation mode.

As such, the continuous operation mode Pona in which the defrost heater 330 is continuously turned on and the pulse operation mode in which the defrost heater 330 is repeatedly turned on and off are controlled to be performed according to the change rate of the temperature detected by the temperature sensor 320, and the defrosting efficiency and power consumption may be improved by performing defrosting based on the change rate ΔT of the temperature.

In particular, since defrosting is performed according to the actual amount of frost on the evaporator 122, defrosting efficiency and power consumption may be improved.

FIGS. 7A to 13 are diagrams referenced in the description of FIG. 6.

FIG. 7A is a diagram illustrating a defrost heater HT and a switch RL for driving a defrost heater when one evaporator and one defrost heater are used in the refrigerator 100.

Referring to the drawing, when only one freezer compartment evaporator 122 is used in the refrigerator 100, the freezer compartment defrost heater HT may operate to remove frost attached to the freezer compartment evaporator 122.

To this end, the switch RL in the heater driver 332 may control the operation of the defrost heater HT. In this case, the switch RL may be a relay.

That is, when the switch RL is continuously turned on, the continuous operation mode Pona in which the defrost heater HT is continuously turned on may be performed, and when the switch RL is switched on and off, the pulse operation mode Ponb in which the defrost heater HT is repeatedly turned on and off may be performed.

Next, FIG. 7B is a diagram illustrating defrost heaters HTa and HTb and switches RLa and RLb for driving the defrost heaters when two evaporators and two defrost heaters are used in the refrigerator 100.

When a first defrost heater HTa is a freezer compartment defrost heater, a first switch RLa in the heater driver 332 may control the operation of the first defrost heater HTa. In this case, the first switch RLa may be a relay.

That is, when the first switch RLa is continuously turned on, the continuous operation mode Pona in which the first defrost heater HTa is continuously turned on may be performed, and when the first switch RLa performs on and off switching, the pulse operation mode Ponb in which the first defrost heater HTa is repeatedly turned on and off may be performed.

When a second defrost heater HTb is a refrigerating compartment defrost heater, a second switch RLb in the heater driver 332 may control the operation of the second defrost heater HTb. In this case, the second switch RLb may be a relay.

That is, when the second switch RLb is continuously turned on, the continuous operation mode Ponb in which the second defrost heater HTb is continuously turned on may be performed, and when the second switch RLb performs on and off switching, the pulse operation mode Ponb in which the second defrost heater HTb is repeatedly turned on and off may be performed.

Meanwhile, on and off timings of the first switch RLa and the second switch RLb may be different from each other. Accordingly, it may be possible to perform the defrosting of

the freezer compartment evaporator and the defrosting of the refrigerating compartment evaporator, separately.

FIG. 8A is a diagram illustrating an example of a pulse waveform indicating an operation of one defrost heater of FIG. 7A.

Referring to the drawings, the horizontal axis of the pulse waveform Psh may represent time and the vertical axis may represent a level.

When the defrosting start time To arrives, while performing the normal cooling operation mode Pga, the controller 310 of the refrigerator 100 may end the normal cooling operation mode Pga and control to perform the defrost operation mode pdf.

The defrost operation mode pdf may include a pre-defrost cooling mode Pbd between To and Ta, a heater operation mode PddT between Ta and Td, and a post-defrost cooling mode pbf between Td and Te.

Meanwhile, after the defrost operation mode pdf is ended, the normal cooling operation mode Pgb is performed again.

The defrost heater 330 is turned off in the normal cooling operation mode Pga and the normal cooling operation mode Pgb.

Meanwhile, the defrost heater 330 may be turned off in the pre-defrost cooling mode Pbd and the post-defrost cooling mode pbf of the defrost operation mode Pdf.

Meanwhile, the defrost heater 330 may be continuously turned on in the continuous operation mode Pona of the heater operation mode PddT, and may be repeatedly turned on and off in the pulse operation mode Ponb of the heater operation mode PddT.

The continuous operation mode Pona may be performed between Ta and Tb, and the pulse operation mode Ponb may be performed between Tb and Tc.

When only the continuous operation mode is performed and the defrost heater 330 is continuously turned on, if the amount of frost is large, defrosting may not be performed properly or if the amount of frost is small, unnecessary defrosting may be performed, and thus, unnecessary power consumption may be consumed.

Accordingly, in the present disclosure, the continuous operation mode Pona and the pulse operation mode Ponb are used in combination. Accordingly, defrosting efficiency and power consumption may be improved.

FIG. 8B is a diagram illustrating an example of a pulse waveform indicating an operation of two defrost heaters of FIG. 7B.

Referring to the drawing, (a) of FIG. 8B shows a pulse waveform Psha indicating an operation of the freezer compartment defrost heater, and (b) of FIG. 8B shows a pulse waveform Pshb indicating an operation of the refrigerating compartment defrost heater.

The pulse waveform Psha of (a) of FIG. 8B may be the same as the pulse waveform Psh of FIG. 8A.

Meanwhile, since less frost may occur in the refrigerating compartment evaporator than in the freezer compartment evaporator, an operating section of the refrigerating compartment defrost heater may be smaller than an operating section of the freezer compartment defrost heater.

Referring to the pulse waveform Pshb of (b) of FIG. 8B, a period of continuously turning on in the continuous operation mode Pona in the heater operation mode PddT may be less than that of a corresponding period of continuously turning on in the pulse waveform Psha of (a) of FIG. 8B.

In addition, referring to the pulse waveform Pshb of (b) of FIG. 8B, an ON/OFF repetition period of the pulse operation mode Ponb in the heater operation mode PddT may be less

than that of a corresponding ON/OFF repetition period in the pulse waveform P_{sha} of (a) of FIG. 8B.

FIG. 9 is a diagram illustrating an example of cooling power supply and a defrost heater operation in the defrost operation mode P_{df} of FIG. 8A.

Referring to the drawing, the defrost operation mode P_{df} may include a pre-defrost cooling mode P_{bd} between T_0 and T_a , a heater operation mode P_{ddT} between T_a and T_d , and a post-defrost cooling mode P_{bf} between T_d and T_e .

During a period T_0 to T_1 of the pre-defrost cooling mode P_{bd} , a level of supplied cooling power may be an R level, and during a period T_1 to T_2 , a level of supplied cooling power may be an F level that is greater than the R level.

Also, during a period T_2 to T_3 of the pre-defrost cooling mode P_{bd} , the cooling power supply may be stopped.

In addition, during a period T_3 to T_a in the pre-defrost cooling mode P_{bd} , a level of supplied cooling power may be the R level.

According to the pre-defrost cooling mode P_{bd} , the supplied cooling power to compensate for the stoppage of cooling power supply during the heater operation mode P_{ddT} is performed.

Meanwhile, the cooling power supply may be performed by a compressor, a thermoelectric element, or the like, and in the drawings, it is illustrated that the cooling power supply is performed by an operation of the compressor.

During a period T_0 to T_2 and T_3 to T_a in which the cooling power is supplied, the compressor operates, and during a period T_2 to T_3 in which the cooling power is not supplied, the compressor is turned off.

Meanwhile, during a period T_0 to T_1 in which the cooling power of R level is supplied, the refrigerating compartment fan may operate and the freezer compartment fan may be turned off.

Meanwhile, during a period from a time point T_1 , at which the cooling power of F level is supplied, to a time point T_a , at which the pre-defrost cooling mode P_{bd} is ended, the refrigerating compartment fan may be turned off and the freezer compartment fan may be operated.

Meanwhile, during the period T_2 to T_a , the defrost heater 330 may be maintained in an OFF state.

Next, the defrost heater 330 may operate during the period of T_a to T_c in the period of T_a to T_d of the heater operation mode P_{ddT} .

As shown in FIG. 8A, the continuous operation mode P_{ona} may be performed during the period of T_a to T_b of the heater operation mode P_{ddT} period, and the heater operation mode P_{ddT} may be performed during the period starting at T_b and the period starting at T_c .

Meanwhile, the defrost heater 330 may be turned off from T_c , which is an end time point of the continuous operation mode P_{ona} , to T_d .

Meanwhile, during the period of the heater operation mode P_{ddT} , the compressor and the refrigerating compartment fan may be turned off.

Meanwhile, during the period of the heater operation mode P_{ddT} , the freezer compartment fan may be turned off. In particular, it is preferable that the freezer compartment fan is turned off from T_c , which is the end time point of the continuous operation mode P_{ona} , to T_d .

After the heater operation mode P_{ddT} , the post-defrost cooling mode P_{bf} is performed.

During the period of T_d to T_4 in the post-defrost cooling mode P_{bf} , a level of the supplied cooling power may be an $R+F$ level, and the largest level of cooling power may be supplied.

In addition, during the period of T_4 to T_6 in the post-defrost cooling mode P_{bf} , a level of the supplied cooling power may be F level, and the cooling power supply may be stopped during the period T_6 to T_e .

According to the post-defrost cooling mode P_{bf} , the largest level of cooling power supply may be performed according to the stopping of the cooling power supply during the heater operation mode P_{ddT} .

During the period of T_d to T_6 in which the cooling power is supplied, the compressor operates, and the compressor is turned off during the period of T_6 to T_e in which the cooling power is not supplied.

Meanwhile, during the period of T_d to T_4 in which the cooling power of $R+F$ level is supplied, the refrigerating compartment fan and the freezer compartment fan may be turned on together.

Meanwhile, during the period of T_4 to T_6 in which the cooling power of F level is supplied, the refrigerating compartment fan may be turned off and the freezer compartment fan may be operated.

Meanwhile, the level of power consumption in the heater operation mode P_{ddT} in FIG. 9 may be greater than the level of power consumption of the cooling power of $R+F$ level.

FIG. 10 is a diagram illustrating temperature change waveforms of an evaporator in response to the defrost heater being operated only in the continuous operation mode and when the continuous operation mode and the pulse operation mode are mixed.

In particular, in (a) of FIG. 10, CV_a represents a temperature change waveform in response to the defrost heater being operated only in the continuous operation mode, and CV_b represents a temperature change waveform in response to the defrost heater being operated by mixing the continuous operation mode and the pulse operation mode.

According to CV_a , the defrost heater 330 is continuously turned on, and may be turned off at a time point T_x , as shown in (b) of FIG. 10.

According to CV_b , the defrost heater 330 operates during the Pohm period, as shown in (c) of FIG. 10.

That is, during the Pohm period including up to a T_{pa} time point, the continuous operation mode is performed, and the pulse operation mode is performed during a P_{ofn} period from T_{pa} to T_{pb} .

$Trf1$ represents a phase-change temperature, and may be, for example, $0^\circ C$. Meanwhile, $Trf2$ represents a defrost end temperature, for example, may be $5^\circ C$.

Meanwhile, a region between $Trf1$ and $Trf2$ may indicate a defrosting region in which defrosting is actually performed, and a region exceeding $Trf2$ may indicate an overheating region in which excessive defrosting is performed.

In order to actually effectively perform defrosting, it is preferable that a size of the overheating region is reduced and a size of the defrosting region is increased.

Accordingly, in the present disclosure, the continuous operation mode and the pulse operation mode of the defrost heater 300 are mixed in order to reduce the size of the overheating region and increase the size of the defrosting region.

Meanwhile, the controller 310 may be configured to control a peak temperature arrival point Q_d of the evaporator 122, when the continuous operation mode P_{ona} and the pulse operation mode P_{onb} are performed in the defrost operation mode P_{df} , to be later than a peak temperature arrival point Q_c of the evaporator 122, when the defrost heater 330 is only continuously turned on in the defrost operation mode P_{df} . Accordingly, it may be possible to improve the defrosting efficiency and power consumption

when the continuous operation mode Pona and the pulse operation mode Ponb are performed.

Meanwhile, the controller 310 may be configured to control a size of a second section Arbb related to a temperature against time between a phase-change temperature Trf1 and a defrost end temperature Trf2 in response to the continuous operation mode and the pulse operation mode being performed in the defrosting operation mode Pdf to be greater than a size of a first section Arab related to a temperature against time between the phase-change temperature Trf1 and the defrost end temperature Trf2 in response to the defrost heater being only continuously turned on in the defrost operation mode Pdf. Accordingly, it may be possible to improve the defrosting efficiency and power consumption when the continuous operation mode Pona and the pulse operation mode Ponb are performed.

Meanwhile, the controller 310 may be configured to control an effective defrosting when the continuous operation mode Pona and the pulse operation mode Ponb are performed in the defrost operation mode Pdf that is greater than an effective defrosting when the defrost heater 330 is only continuously turned on in the defrost operation mode Pdf. Accordingly, it may be possible to improve the defrosting efficiency and power consumption when the continuous operation mode Pona and the pulse operation mode Ponb are performed.

Meanwhile, the controller 310 may be configured to control a heater OFF time point Tpb when the continuous operation mode Pona and the pulse operation mode Ponb are performed in the defrost operation mode Pdf to be later than a heater OFF time point Tx when the defrost heater 330 is only continuously turned on in the defrost operation mode Pdf. Accordingly, it may be possible to improve the defrosting efficiency and power consumption when the continuous operation mode Pona and the pulse operation mode Ponb are performed.

Meanwhile, the controller 310 may be configured to control a period Tpb-Qd between the heater OFF time point Tpb and a peak temperature arrival time Qd of the evaporator 122 when the continuous operation mode Pona and the pulse operation mode Ponb are performed in the defrost operation mode Pdf to be greater than a period Tx-Qc between the heater OFF time point and the peak temperature arrival time Qc of the evaporator 122 when the defrost heater 330 is only continuously turned on in the defrost operation mode Pdf. Accordingly, it may be possible to improve the defrosting efficiency and power consumption when the continuous operation mode Pona and the pulse operation mode Ponb are performed.

Meanwhile, the controller 310 may be configured to control a period Tpb-Qh between the heater OFF time point Tpb to a time point at which a temperature falls below a phase-change temperature Trf1 when the continuous operation mode Pona and the pulse operation mode Ponb are performed in the defrost operation mode Pdf to be less than a period Tx-Qg between the heater OFF time point Tx to a time point Qg at which the temperature falls below the phase-change temperature Trf1 when the defrost heater 330 is only continuously turned on in the defrost operation mode Pdf. Accordingly, it may be possible to improve the defrosting efficiency and power consumption when the continuous operation mode Pona and the pulse operation mode Ponb are performed.

Meanwhile, the controller 310 may be configured to control a size of an overheat temperature region Arba equal to higher than the defrosting end temperature Trf2 when the continuous operation mode Pona and the pulse operation

mode Ponb are performed in the defrost operation mode Pdf to be less than an overheat temperature region Araa equal to higher than the defrosting end temperature Trf2 when the defrost heater 330 is only continuously turned on in the defrost operation mode Pdf. Accordingly, it may be possible to improve the defrosting efficiency and power consumption when the continuous operation mode Pona and the pulse operation mode Ponb are performed.

In FIG. 10, (d) shows a cooling power supply waveform COa in the case of only continuously turning on the defrost heater 330 and a cooling power supply waveform COb in the case of performing a continuous operation mode Pona and a pulse operation mode Ponb.

Referring to the drawing, the controller 310 may be configured to control a cooling power supply time point Tcb according to a normal cooling operation mode Pga when the continuous operation mode Pona and the pulse operation mode Ponb are performed in the defrost operation mode Pdf to be later than a cooling power supply time point Tca according to the normal cooling operation mode Pga when the defrost heater 330 is only continuously turned on in the defrost operation mode Pdf. Accordingly, it is possible to improve the defrosting efficiency and power consumption when the continuous operation mode Pona and the pulse operation mode Ponb are performed.

FIG. 11 is a flowchart illustrating an operating method in a pulse operation mode according to an embodiment of the present disclosure.

Referring to the drawing, the controller 310 controls the defrost heater 330 to be turned on based on the heater operation mode, in particular, based on the continuous operation mode (S1115).

Next, the controller 310 calculates a change rate ΔT of a temperature detected by the temperature sensor 320 during the operation of the defrost heater 330, and determines whether the change rate ΔT of the temperature is equal to or greater than a first reference value ref1 (S1120).

For example, when the change rate ΔT of the temperature during the continuous operation of the defrost heater 330 is less than the first reference value ref1, the controller 310 may control the defrost heater 330 to continuously operate.

Meanwhile, when the change rate ΔT of the temperature during the continuous operation of the defrost heater 330 is equal to or greater than the first reference value ref1, the controller 310 may temporarily turn off the defrost heater 330 (S1125).

Next, the controller 310 calculates the change rate ΔT of the temperature detected by the temperature sensor 320 after the defrost heater 330 is temporarily turned off, and determine whether the change rate ΔT of the temperature is less than or equal to a second reference value ref2 (S1128).

When the change rate ΔT of the temperature detected by the temperature sensor 320 is less than or equal to the second reference value ref2 after the defrost heater 330 is temporarily turned off, the controller 310 is configured to turn on the defrost heater. That is, the controller 310 controls to perform step S1115.

As such, when steps 1115 to 1128 are repeated, the pulse operation mode of the defrost heater 330 is performed.

Meanwhile, in step S1128, after the defrost heater 330 is temporarily turned off, when the change rate ΔT of the temperature exceeds the second reference value ref2, the controller 310 determines a pulse operation mode end condition is met. When the pulse operation mode end condition is met (S1130), the controller 310 ends the pulse operation mode and controls the heater to be turned off (S1140).

The pulse operation mode end condition may correspond to the pulse operation mode end time point.

For example, the pulse operation mode end time point may be a time at which the temperature detected by the temperature sensor 320 falls below the phase-change temperature Trf1.

As another example, the pulse operation mode end time point may be an end time point of the defrosting operation or an end time point of the heater operation mode.

Meanwhile, when the defrosting operation start time point 10 arrives, the controller 310 controls to perform the defrost operation mode Pdf and controls to perform the continuous operation mode Pona in which the defrost heater 330 is continuously turned on and the pulse operation mode Ponb in which the defrost heater 330 is repeatedly turned on and off according to the defrost operation mode Pdf, and when performing the pulse operation mode Ponb, the controller controls the defrost heater 330 to be turned on and off according to the change rate ΔT of the temperature detected by the temperature sensor 320. Accordingly, since defrosting 15 may be performed based on the change rate ΔT of the temperature, it may be possible to improve defrost efficiency and power consumption.

In particular, since defrosting is performed according to the actual amount of frost ICE on the evaporator 122, it may be possible to improve defrost efficiency and power consumption.

Meanwhile, the controller 310 may control to perform the continuous operation mode Pona or the pulse operation mode Ponb according to the change rate ΔT of the temperature detected by the temperature sensor 320. Accordingly, it may be possible to improve the defrosting efficiency and power consumption.

Meanwhile, the controller 310 may control the heater to be driven with power inversely proportional to the change rate ΔT of the temperature detected by the sensor during the pulse operation mode Ponb. Accordingly, it may be possible to improve the defrosting efficiency and power consumption.

Meanwhile, the controller 310 may control a period of performing the defrost operation mode Pdf to be decreased as the number of opening times of the cooling compartment door increases. Accordingly, it may be possible to improve the defrosting efficiency and power consumption.

FIG. 12A is a diagram showing a temperature waveform of the evaporator when there is a large amount of frost formation.

In FIG. 12A, (a), CVma represents a temperature change waveform in response to the defrost heater being operated only in the continuous operation mode, and CVmb represents a temperature change waveform in response to the defrost heater being operated by mixing the continuous operation mode and the pulse operation mode.

According to CVma, the defrost heater 330 may be continuously turned on, and may be turned off at a time point Tmg, as shown in (b) of FIG. 12A.

According to CVmb, as shown in (c) of FIG. 12A, the defrost heater 330 is continuously turned on during a period ending in Tma and turned off during Tma and Tmb, during Tmc and Tmd, during Tme and Tmf, and during Tmg and Tmh, and the defrost heater 330 is turned on during Tmb and Tmc, during Tmd and Tme, during Tmf and Tmg, and during Tmh and Tmi.

That is, from Tma to Tmi, the defrost heater 330 operates in the pulse operation mode.

Meanwhile, the controller 310 controls the defrost heater 330 to be continuously turned on based on the continuous

operation mode Pona, and in the ON state of the defrost heater 330, when the change rate ΔT of the ambient temperature of the evaporator 122 detected by the temperature sensor 320 is equal to or greater than the first reference value ref1, the controller 310 may enter the pulse operation mode Ponb and control the defroster heater 330 to be turned off. Accordingly, it may be possible to improve the defrosting efficiency and power consumption.

Meanwhile, when the defrost heater 330 is turned off 10 during the pulse operation mode Ponb and the change rate ΔT of the temperature around the evaporator 122 is equal to or less than the second reference value ref2 that is smaller than the first reference value ref1, the controller 310 may control the defrost heater 330 to be turned on. Accordingly, it may be possible to improve the defrosting efficiency and power consumption.

Meanwhile, when the defrost heater 330 is turned on 20 during the pulse operation mode Ponb and the change rate ΔT of the temperature around the evaporator 122 is equal to or greater than the first reference value ref1, the controller 310 may control the defrost heater 330 to be turned on. Accordingly, it may be possible to improve the defrosting efficiency and power consumption.

Meanwhile, the controller 310 may control the defrost heater 330 to be continuously turned on based on the continuous operation mode Pona, and based on the pulse operation mode Ponb, the controller 310 may repeatedly turned on and off the defrost heater 330 so that the change rate ΔT of the temperature around the evaporator 122 may be between the first reference value ref1 and the second reference value ref2. Accordingly, it may be possible to improve the defrosting efficiency and power consumption.

FIG. 12B is a diagram showing a temperature waveform of the evaporator when the amount of frost formation is smaller than that of FIG. 12A.

In (a) of FIG. 12B, CVna represents a temperature change waveform in response to the defrost heater being operated only in the continuous operation mode, and CVnb represents a temperature change waveform in response to the defrost heater being operated by mixing the continuous operation mode and the pulse operation mode.

According to CVna, the defrost heater 330 may be continuously turned on and may be turned off at a time point Tnf, as shown in (b) of FIG. 12B.

According to CVnb, as shown in (c) of FIG. 12b, the defrost heater 330 is continuously turned on during a period ending in Tna, and the defrost heater 330 is turned off during Tna and Tnb, during Tnc and Tnd, during Tne and Tng, and during Tnh and Tni, and turned on during Tnb and Tnc, during Tnd and Tne, during Tng and Tnh, and during Tni and Tnj.

That is, from Tna to Thj, the defrost heater 330 operates in the pulse operation mode.

FIG. 13 is a view showing a region requiring cooling power supply and a region requiring defrosting according to temperatures of the refrigerating compartment and the freezer compartment.

Referring to the drawing, the horizontal axis may indicate a temperature of the refrigerating compartment, and the vertical axis may indicate a temperature of the freezer compartment.

When a temperature is equal to or lower than a reference 60 temperature of the freezer compartment refma, it may indicate that a freezing capacity is sufficient, and when the temperature is equal to or lower than a reference temperature

of the refrigerating compartment refmb, it may indicate that cooling capacity of the refrigerating compartment is sufficient.

An Arma region in the drawing is a region in which freezing capacity of the freezer compartment and cooling capacity of the refrigerating compartment are sufficient, and may be a region requiring defrosting.

Accordingly, when the defrosting required region is satisfied based on the temperature of the refrigerating compartment and the freezer compartment, the controller 310 may control to perform the continuous operation mode and the pulse operation mode described above. In particular, ON/OFF of the defrost heater 330 in the pulse operation mode may be controlled based on a temperature change rate around the evaporator 122.

Meanwhile, the Armb region in the drawing may be a region in which both cooling power of the freezer compartment and cooling power of the refrigerating compartment are insufficient, and may be a cooling power supply requiring region requiring cooling power supply.

Accordingly, the controller 310 may control supply of cooling power. For example, a compressor may be operated or a thermoelectric element may be operated to control the supply of cooling power.

FIG. 14 is a flowchart illustrating a method of defrosting and cooling after defrosting according to an embodiment of the present disclosure, and FIGS. 15A to 15D are views referenced in the description of FIG. 14.

Referring to FIG. 14, the controller 310 of the refrigerator 100 according to an embodiment of the present disclosure determines whether a defrosting operation start time point arrives for defrosting (S610).

For example, the controller 310 of the refrigerator 100 may determine whether a defrosting operation start time point arrives, while performing the normal cooling operation mode Pga. The defrosting operation start time point may vary according to a defrost cycle.

Meanwhile, when a defrosting operation start condition is satisfied, for example, in response to a defrosting operation start time point arriving, the controller 310 of the refrigerator 100 may end the normal cooling operation mode and control to perform the defrost operation mode Pdf.

Meanwhile, the defrost operation mode Pdf may include a pre-defrost cooling mode Pbd, a heater operation mode PddT, and a post-defrost cooling mode pbf.

The heater operation mode PddT may include a continuous operation mode Pona in which the defrost heater 330 is continuously turned on, and a pulse operation mode Ponb in which the defrost heater 330 is repeatedly turned on and off.

Meanwhile, the controller 310 of the refrigerator 100 may control the defrost heater 330 to be continuously turned on based on the continuous operation mode Pona in the heater operation mode PddT of the defrost operation mode Pdf (S615).

Next, after the continuous ON of the defrosting heater 330, the controller 310 of the refrigerator 100 may control to perform the pulse operation mode in which the defrost heater 330 is repeatedly turned on and off by a pulse operation of the defrost heater (S620).

Next, the controller 310 of the refrigerator 100 determines whether a pulse operation mode end time point arrives (S630), and when the pulse operation mode end time point arrives, the controller 310 of the refrigerator 100 turns off the defrost heater 330 (S640).

For example, the pulse operation mode end time point may be a time point at which the temperature detected by the temperature sensor 320 falls below the phase-change temperature Trf1.

As another example, the pulse operation mode end time point may be an end time point of the defrosting operation or an end time point of the heater operation mode.

Next, the controller 310 of the refrigerator 100 changes a magnitude of cooling power supplied in the post-defrost cooling mode Pbf based on an ON period of the defrost heater 330 in the pulse operation mode Ponb or a temperature of the cooling compartment (S650).

For example, the controller 310 controls so that cooling power supplied in the post-defrost cooling mode pbf increases as the ON period of the defrost heater 330 in the pulse operation mode Ponb increases or the temperature of the cooling compartment increases.

When the ON period of the defrost heater 330 in the pulse operation mode Ponb increases, a duration of the defrost operation mode is increased, and thus a period during which the supply of cooling power is stopped increases. Therefore, it is preferable to maintain the set temperature in the refrigerator by increasing the magnitude of cooling power supplied in the post-defrost cooling mode Pbf.

Therefore, through the pulse operation mode Ponb, the defrost efficiency and power consumption may be improved, and the cooling power after defrost may be efficiently supplied by varying the magnitude of cooling power supplied in the post-defrost cooling mode pbf.

As another example, when the ON period of the defrost heater 330 in the pulse operation mode Ponb or the temperature of the cooling compartment is lower than or equal to a set value, the controller 310 may be configured to change the magnitude of cooling power supplied in the post-defrost cooling mode Pbf based on the ON period of the defrost heater 330 or the temperature of the cooling compartment, and when the ON period of the defrost heater 330 in the pulse operation mode Ponb or the temperature of the cooling compartment exceeds the set value, the controller 310 may be configured to supply maximum cooling power in the post-defrost cooling mode pbf. Accordingly, it may be possible to improve defrosting efficiency, improve power consumption, and efficiently supply cooling power after defrosting.

Meanwhile, in response to the temperature of the cooling compartment being equal to or lower than the cooling compartment reference temperature after performing the pulse operation mode Ponb, the controller 310 may be configured to increase the magnitude of cooling power supplied in the post-defrost cooling mode Pbf as the temperature of the cooling compartment increases. Accordingly, it may be possible to efficiently supply cooling power after defrosting.

Meanwhile, in response to the temperature of the cooling compartment exceeding the cooling compartment reference temperature after the pulse operation mode Ponb is performed, the controller 310 may be configured to supply maximum cooling power, rather than varying the magnitude of cooling power. Accordingly, it may be possible to efficiently supply cooling power after defrosting.

Meanwhile, after the pulse operation mode Ponb, the controller 310 may be configured to change the magnitude of cooling power supplied in the post-defrost cooling mode pbf in inverse proportion to a difference between the set temperature and the temperature of the cooling compartment.

For example, when the temperature of the cooling compartment rises after the pulse operation mode Ponb, the difference between the set temperature and the temperature of the cooling compartment increases, and thus the controller 310 may be configured to increase the magnitude of cooling power supplied in the post-defrost cooling mode pbf. Accordingly, it may be possible to efficiently supply cooling power after defrosting.

Meanwhile, when the continuous operation mode Pona is performed after the pulse operation mode Ponb, the controller 310 may be configured to control the magnitude of cooling power supplied in the post-defrost cooling mode pbf to increase to be greater than that when only the pulse operation mode Ponb is performed.

For example, when the continuous operation mode Pona is performed after the pulse operation mode Ponb, a duration of the heater operation mode is longer than when only the pulse operation mode Ponb is performed, and as a result, a cooling power interruption period is lengthened. Accordingly, it may be preferable to control the magnitude of cooling power supplied in the post-defrost cooling mode Pbf to be larger.

Meanwhile, when the pulse operation mode Ponb is performed after the continuous operation mode Pona, the controller 310 may be configured to control the magnitude of cooling power supplied in the post-defrost cooling mode pbf to be larger than that when only the pulse operation mode Ponb is performed.

For example, when the pulse operation mode Ponb is performed after the continuous operation mode Pona, the duration of the heater operation mode is longer than when only the pulse operation mode Ponb is performed, and as a result, the cooling power suspension period is lengthened. Accordingly, it may be preferable to control the magnitude of cooling power supplied in the post-defrost cooling mode Pbf to be larger.

Meanwhile, the controller 310 may be configured to change the magnitude of cooling power supplied in the post-defrost cooling mode Pbf in proportion to a door opening period in the pulse operation mode Ponb.

For example, as the door opening period increases during the pulse operation mode Ponb, the cooling compartment temperature increases while cooling power is stopped, and thus, the controller 310 may preferably control the magnitude of cooling power supplied in the post-defrost cooling mode pbf to be increased. Accordingly, it may be possible to efficiently supply cooling power after defrosting.

As another example, as the door opening period increases during the pulse operation mode Ponb, a level of cooling power supplied urgently rather than the cooling power suspension increases, and thus, the controller may control the magnitude of cooling power supplied in the post-defrost cooling mode pbf to be decreased. Accordingly, it may be possible to efficiently supply cooling power after defrosting.

FIG. 15A illustrates the same cooling power waveform Pcv as FIG. 9A.

Referring to the drawing, it is illustrated that an ON period of the defrost heater 330 is between Ta and Tc.

In this case, the ON period of the defrost heater 330 may include the continuous operation mode Pona and the pulse operation mode Ponb.

The controller 310 may determine a level of cooling power in the post-defrost cooling mode Pbf based on the ON period of the defrost heater 330 in the pulse operation mode Ponb.

In the drawing, cooling power of R+F level is supplied between Td and T4 in the post-defrost cooling mode pbf, and

cooling power of F level is supplied between T5 and T6 in the post-defrost cooling mode pbf.

FIG. 15B illustrates a different cooling power waveform Pcvb than FIG. 15A.

Referring to the drawing, it is illustrated that an ON period of the defrost heater 330 is between Ta and Tca.

It can be seen that the ON period of the defrost heater 330 is further increased compared to the cooling power waveform Pcv of FIG. 15A. Accordingly, the period of the pulse operation mode of FIG. 15B is greater in duration than that of the pulse operation mode of FIG. 15A.

Accordingly, the controller 310 may be configured to supply cooling power of M1 level that is greater than the R+F level between Td and T4 in the post-defrost cooling mode pbf and cooling power of F-level is supplied between T5 and T6 in the post-defrost cooling mode pbf.

That is, the controller 310 may control the level of cooling power supplied in the post-defrost cooling mode pbf to increase as the ON period of the defrost heater 330 in the pulse operation mode Ponb increases. Accordingly, it may be possible to efficiently supply cooling power after defrosting.

FIG. 15C illustrates a different cooling power waveform Pcvb than FIG. 15B.

Referring to the drawing, it is illustrated that an ON period of the defrost heater 330 is between Ta and Tcb.

It can be seen that the ON period of the defrost heater 330 is further increased compared to the cooling power waveform Pcvb of FIG. 15B. Accordingly, the period of the pulse operation mode of FIG. 15C is greater than that of the pulse operation mode of FIG. 15B.

Accordingly, the controller 310 may be configured to supply cooling power of M2 level that is greater than the M1 level supplied between Td and T4 in the post-defrost cooling mode pbf, and supply cooling power of F level between T5 and T6 in the post-defrost cooling mode pbf.

FIG. 15D illustrates a different cooling power waveform Pcvb than FIG. 15C.

Referring to the drawing, it is illustrated that an ON period of the defrost heater 330, which is Ta and Tcb, is the same as that of FIG. 15C.

In comparison with FIG. 15C, the controller 310 may be configured to supply cooling power of M2 level that is greater than the M1 level between Td and T4 in the post-defrost cooling mode pbf, and supply cooling power of M1 level that is greater than the F level between T5 and T6 in the post-defrost cooling mode Pbf.

That is, the controller 310 may control the variable cooling power to be supplied throughout the period of the post-defrost cooling mode Pbf.

FIG. 16 is a flowchart illustrating a method of defrosting and cooling after defrosting according to another embodiment of the present disclosure.

Referring to the drawing, the controller 310 of the refrigerator 100 according to an embodiment of the present disclosure determines whether a defrosting operation start time point arrives for defrosting (S610).

For example, the controller 310 of the refrigerator 100 may determine whether it is the defrosting operation start time point, while performing the normal cooling operation mode Pga. The defrosting operation start time point may vary according to a defrost cycle.

Meanwhile, when a defrosting operation start condition is satisfied, for example, in response to a defrosting operation start time point arriving, the controller 310 of the refrigerator 100 may end the normal cooling operation mode and control to perform the defrost operation mode Pdf.

Meanwhile, the controller 310 of the refrigerator 100 may control the defrost heater 330 to be continuously turned on based on the continuous operation mode Pona in the heater operation mode PddT of the defrost operation mode Pdf (S615).

Next, the controller 310 of the refrigerator 100 determines whether the temperature detected by the temperature sensor 320 reaches the reference temperature (S616), and when the temperature detected by the temperature sensor 320 reaches the reference temperature, the controller determines whether an elapsed time until the reference temperature is reached is equal to or less than a reference time (S618), and when the elapsed time until the reference temperature is reached is equal to or less than the reference time, the controller 310 of the refrigerator 100 controls the pulse operation mode to be performed (S620).

For example, the controller 310 of the refrigerator 100 may control the pulse operation mode to be performed based on the elapsed time until the reference temperature is reached.

Accordingly, the on and off of the defrost heater 330 may be repeated.

Next, the controller 310 of the refrigerator 100 determines whether the defrost end temperature is reached (S622), and when the defrost end temperature is reached, the controller 310 of the refrigerator 100 ends the defrosting (S624).

Accordingly, the controller 310 may turn off the defrost heater 330. Also, the controller 310 may control to perform post-defrost cooling.

Meanwhile, the controller 310 determines whether an ON period of the defrost heater 330 in the pulse operation mode Ponb or a temperature of the cooling compartment is less than or equal to a set value (S645), and when the ON period of the defrost heater 330 in the pulse operation mode Ponb or the temperature of the cooling compartment is less than or equal to the set value, the controller 310 changes a magnitude of cooling power supplied in the post-defrost cooling mode pbf (S650).

Meanwhile, when the ON period of the defrost heater 330 in the pulse operation mode Ponb or the temperature of the cooling compartment is not equal to or less than the set value, for example, when they exceeds the set value, the controller controls so that maximum cooling power is output in the post-defrost cooling mode pbf (S652). Accordingly, it may be possible to efficiently supply cooling power after defrosting.

Meanwhile, in response to the temperature of the cooling compartment being equal to or less than the cooling compartment reference temperature, the controller 310 may be configured to change the magnitude of cooling power supplied in the post-defrost cooling mode Pbf based on the ON period of the defrost heater 330 or the temperature of the cooling compartment, and in response to the temperature of the cooling compartment exceeding the cooling compartment reference temperature, the controller 310 may be configured to supply maximum cooling power in the post-defrost cooling mode Pbf. Accordingly, defrosting efficiency may be improved, power consumption may be improved, and cooling power after defrosting may be efficiently supplied.

Meanwhile, when the temperature of the refrigerating compartment is equal to or lower than the refrigerating compartment reference temperature refmb and the temperature of the freezer compartment is equal to or lower than the freezer compartment reference temperature refma, that is, when it corresponds to the Arma region of FIG. 13A, the controller 310 may be configured to change the magnitude

of cooling power supplied in the post-defrost cooling mode pbf based on the ON period of the defrost heater 330 or the temperature of the cooling compartment. Accordingly, it may be possible to efficiently supply cooling power after defrosting.

Meanwhile, in response to the temperature of the refrigerating compartment exceeding the refrigerating compartment reference temperature refmb and the freezer compartment temperature exceeding the freezer compartment reference temperature refma, that is, when it corresponds to the arm region of FIG. 13A, the controller 310 may be configured to supply maximum cooling power in the post-defrost cooling mode pbf. Accordingly, it may be possible to efficiently supply cooling power after defrosting.

FIG. 17 is a flowchart illustrating a method of defrosting and cooling after defrosting according to another embodiment of the present disclosure, and FIGS. 18A to 18E are views referenced in the description of FIG. 17.

Referring to FIG. 17, the controller 310 of the refrigerator 100 according to an embodiment of the present disclosure determines whether it is a defrosting operation start time point for defrosting (S1610).

For example, while performing the normal cooling operation mode Pga, the controller 310 of the refrigerator 100 may determine whether it is the defrosting operation start time point. The defrosting operation start time point may vary according to a defrost cycle.

Meanwhile, when a defrosting operation start condition is satisfied, for example, in response to the defrosting operation start time point arriving, the controller 310 of the refrigerator 100 may end the normal cooling operation mode and control to perform the defrost operation mode Pdf.

Meanwhile, the defrost operation mode Pdf may include a pre-defrost cooling mode Pbd, a heater operation mode PddT, and a post-defrost cooling mode pbf.

The heater operation mode PddT may include a continuous operation mode Pona in which the defrost heater 330 is continuously turned on and a pulse operation mode Ponb in which the defrost heater 330 is repeatedly turned on and off.

Meanwhile, the controller 310 of the refrigerator 100 may control the defrost heater 330 to be continuously turned on based on the continuous operation mode Pona in the heater operation mode PddT in the defrost operation mode Pdf (S1615).

Meanwhile, the controller 310 of the refrigerator 100 may determine whether a cooling compartment door is opened during the continuous operation mode Pona (S1617), and in response to the cooling compartment door being opened during the continuous operation mode Pona, the controller 310 of the refrigerator 100 may control the defrost heater 330 to be turned off (S1642).

For example, in response to the cooling compartment door being opened during the continuous operation mode Pona, the controller 310 of the refrigerator 100 may stop the continuous operation mode Pona and control the defrost heater 330 to be turned off.

As another example, in response to the cooling compartment door being opened during the continuous operation mode Pona and an open period is greater than or equal to a reference period, the controller 310 of the refrigerator 100 may stop the continuous operation mode Pona and control the defrost heater 330 to be turned off.

As another example, in response to the cooling compartment door being opened during the continuous operation mode Pona and the number of opening times of the cooling compartment door is equal to or greater than a reference number of times, the controller 310 of the refrigerator 100

may stop the continuous operation mode Pona and control the defrost heater 330 to be turned off.

Meanwhile, the controller 310 of the refrigerator 100 may stop the heater operation mode PddT according to the interruption of the continuous operation mode Pona, and may control the post-defrost cooling mode pbf to be performed immediately.

The controller 310 of the refrigerator 100 may be configured to supply a predetermined level of cooling power in the post-defrost cooling mode Pbf (S1662). In this case, the predetermined level may correspond to the maximum level. Accordingly, it may be possible to reduce a temperature rise of the cooling compartment due to the opening of the door of the cooling compartment.

The cooling compartment door may be a refrigerating compartment door or a freezer compartment door.

Meanwhile, in response to the cooling compartment door being not opened during the continuous operation mode Pona, the controller 310 of the refrigerator 100 may control the defrost heater 330 to be repeatedly turned on and off based on the pulse operation mode Ponb (S1620). Accordingly, it may be possible to improve the defrost efficiency and improve the power consumption.

Meanwhile, the controller 310 of the refrigerator 100 determines whether the cooling compartment door is opened during the pulse operation mode Ponb (S1623). Also, in response to the cooling compartment door being opened during the pulse operation mode Ponb, the controller 310 of the refrigerator 100 may control the defrost heater 330 to be turned off (S1642).

For example, in response to the cooling compartment door being opened during the pulse operation mode Ponb, the controller 310 of the refrigerator 100 may stop the continuous operation mode Pona and control the defrost heater 330 to be turned off.

As another example, in response to the cooling compartment door being opened during the pulse operation mode Ponb and an open period is greater than or equal to the reference period, the controller 310 of the refrigerator 100 may stop the continuous operation mode Pona and control the defrost heater 330 to be turned off.

As another example, in response to the cooling compartment door being opened during the pulse operation mode Ponb and the number of opening times of the cooling compartment door is equal to or greater than the reference number of times, the controller 310 of the refrigerator 100 may stop the continuous operation mode Pona and control the defrost heater 330 to be turned off.

Meanwhile, the controller 310 of the refrigerator 100 may stop the heater operation mode PddT according to the interruption of the pulse operation mode Ponb, and may control the post-defrost cooling mode pbf to be performed immediately.

The controller 310 of the refrigerator 100 may be configured to supply a predetermined level of cooling power in the post-defrost cooling mode Pbf (S1662). In this case, the predetermined level may correspond to the maximum level. Accordingly, it may be possible to reduce the temperature rise of the cooling compartment due to the opening of the door of the cooling compartment.

Next, the controller 310 of the refrigerator 100 determines whether it is a pulse operation mode end time point (S1630), and if it is the pulse operation mode end time point, the controller 310 of the refrigerator 100 turns off the defrost heater 330 (S1640).

For example, the pulse operation mode end time point may be a time point at which the temperature detected by the temperature sensor 320 falls below the phase-change temperature Trf1.

As another example, the pulse operation mode end time point may be an end time point of the defrosting operation or an end time point of the heater operation mode.

Next, the controller 310 of the refrigerator 100 is configured to change the magnitude of cooling power supplied in the post-defrost cooling mode Pbf based on the ON period of the defrost heater 330 in the pulse operation mode Ponb or the temperature of the cooling compartment (S1650).

For example, the controller 310 may be configured to increase the magnitude of cooling power supplied in the post-defrost cooling mode pbf as the ON period of the defrost heater 330 in the pulse operation mode Ponb increases or the temperature of the cooling compartment increases.

When the ON period of the defrost heater 330 in the pulse operation mode Ponb increases, a duration of the defrost operation mode is increased, and thus a period during which the supply of cooling power is stopped increases. Therefore, it may be preferable to maintain the set temperature in the refrigerator by increasing the magnitude of cooling power supplied in the post-defrost cooling mode Pbf.

Through the pulse operation mode Ponb, the defrost efficiency and power consumption may be improved, and the cooling power after defrost may be efficiently supplied in the post-defrost cooling mode pbf.

As another example, when the ON period of the defrost heater 330 in the pulse operation mode Ponb or the temperature of the cooling compartment is lower than or equal to a set value, the controller 310 may be configured to change the magnitude of cooling power supplied in the post-defrost cooling mode Pbf based on the ON period of the defrost heater 330 or the temperature of the cooling compartment, and when the ON period of the defrost heater 330 in the pulse operation mode Ponb or the temperature of the cooling compartment exceeds the set value, the controller 310 may be configured to supply maximum cooling power in the post-defrost cooling mode pbf. Accordingly, it may be possible to improve defrosting efficiency, improve power consumption, and efficiently supply cooling power after defrosting.

Meanwhile, in response to the temperature of the cooling compartment being equal to or lower than the cooling compartment reference temperature after performing the pulse operation mode Ponb, the controller 310 may be configured to increase the magnitude of cooling power supplied in the post-defrost cooling mode Pbf as the temperature of the cooling compartment increases. Accordingly, it may be possible to efficiently supply cooling power after defrosting.

Meanwhile, in response to the temperature of the cooling compartment exceeding the cooling compartment reference temperature after the pulse operation mode Ponb is performed, the controller 310 may be configured to supply maximum cooling power, rather than varying the magnitude of cooling power. Accordingly, it may be possible to efficiently supply cooling power after defrosting.

Meanwhile, after the pulse operation mode Ponb, the controller 310 may be configured to change the magnitude of cooling power supplied in the post-defrost cooling mode pbf in inverse proportion to a difference between the set temperature and the temperature of the cooling compartment.

For example, when the temperature of the cooling compartment rises after the pulse operation mode Ponb, the difference between the set temperature and the temperature of the cooling compartment increases, so the controller 310 may be configured to increase the magnitude of cooling power supplied in the post-defrost cooling mode pbf. Accordingly, it may be possible to efficiently supply cooling power after defrosting.

Meanwhile, when the continuous operation mode Pona is performed after the pulse operation mode Ponb, the controller 310 may be configured to increase the magnitude of cooling power supplied in the post-defrost cooling mode pbf to be greater than that when only the pulse operation mode Ponb is performed.

For example, when the continuous operation mode Pona is performed after the pulse operation mode Ponb, a duration of the heater operation mode is longer than when only the pulse operation mode Ponb is performed, and as a result, a cooling power interruption period is lengthened. Accordingly, it may be preferable to control the magnitude of cooling power supplied in the post-defrost cooling mode Pbf to be larger.

Meanwhile, when the pulse operation mode Ponb is performed after the continuous operation mode Pona, the controller 310 may be configured to control the magnitude of cooling power supplied in the post-defrost cooling mode pbf to be larger than that when only the pulse operation mode Ponb is performed.

For example, when the pulse operation mode Ponb is performed after the continuous operation mode Pona, the duration of the heater operation mode is longer than when only the pulse operation mode Ponb is performed, and as a result, the cooling power suspension period is lengthened. Accordingly, it may be preferable to control the magnitude of cooling power supplied in the post-defrost cooling mode Pbf to be larger.

Meanwhile, the controller 310 may be configured to change the magnitude of cooling power supplied in the post-defrost cooling mode Pbf in proportion to a door opening period in the pulse operation mode Ponb.

For example, as the door opening period increases during the pulse operation mode Ponb, the cooling compartment temperature increases while cooling power is stopped, and thus, the controller 310 may preferably control the magnitude of cooling power supplied in the post-defrost cooling mode pbf to be increased. Accordingly, it may be possible to efficiently supply cooling power after defrosting.

As another example, as the door opening period increases during the pulse operation mode Ponb, a level of cooling power supplied urgently rather than the cooling power suspension increases, and thus, the controller may control the magnitude of cooling power supplied in the post-defrost cooling mode pbf to be decreased. Accordingly, it may be possible to efficiently supply cooling power after defrosting.

Meanwhile, in the post-defrost cooling mode pbf, the controller 310 of the refrigerator 100 may determine whether a cooling power varying release condition is satisfied while the cooling power changes (S1655), and when cooling power variable release condition is satisfied, the controller 310 of the refrigerator 100 may be configured to supply a predetermined level of cooling power (S1660). In this case, the predetermined level may correspond to a maximum level.

For example, in response to the cooling compartment door being opened in the post-defrost cooling mode pbf, the

controller 310 of the refrigerator 100 may stop varying the cooling power and control so that the maximum level of cooling power is supplied.

As another example, in the post-defrost cooling mode pbf, when an internal temperature of the cooling compartment is higher than or equal to an allowable temperature higher than a target temperature, the controller 310 of the refrigerator 100 may stop varying the cooling power and control so that the maximum level of cooling power is supplied. Accordingly, it may be possible to quickly control the internal temperature to reach the target temperature during cooling.

FIG. 18A illustrates an example of a cooling power waveform.

Referring to the drawing, the controller 310 of the refrigerator 100 may be configured to perform the pre-defrost cooling mode Pbd between To and Ta, the heater operation mode PddTj is performed between Ta and Tdj, and the post-defrost cooling mode pbfj is performed between Tdj and Tej.

In particular, the controller 310 of the refrigerator 100 controls the defrost heater 330 to be continuously turned on in the continuous operation mode Ponj of the heater operation mode PddTj, and in response to the cooling compartment door being opened at the time Tj, the controller 310 of the refrigerator 100 may control the defrost heater 330 to be turned off.

In addition, the controller 310 of the refrigerator 100 may end the heater operation mode PddTj and control the post-defrost cooling mode pbfj to be performed.

In particular, when the defrost heater 330 is turned off and the post-defrost cooling mode pbfj is performed according to the opening of the cooling compartment door in the continuous operation mode Ponj, the controller 310 of the refrigerator 100 may be configured to supply a predetermined level of cooling power. Here, the predetermined level may be cooling power corresponding to a maximum supplyable level Max. Accordingly, it may be possible to efficiently supply cooling power after defrosting.

FIG. 18B illustrates another example of a cooling power waveform.

Referring to the drawing, the controller 310 of the refrigerator 100 may control to perform a pre-defrost cooling mode Pbd between To and Ta, a heater operation mode PddTk between Ta and Tdk, and a post-defrost cooling mode pbdk between Tdk and Tek.

Meanwhile, the controller 310 of the refrigerator 100 controls the defrost heater 330 to be continuously turned on in the continuous operation mode Ponak of the heater operation mode PddTk, and the pulse operation mode Ponbk is performed after the continuous operation mode Ponak.

Meanwhile, in response to the cooling compartment door being opened at the time Tk while the pulse operation mode Ponbk is performed, the controller 310 of the refrigerator 100 may control the defrost heater 330 to be turned off.

In addition, the controller 310 of the refrigerator 100 may end the heater operation mode PddTk and control the post-defrost cooling mode pbdk to be performed.

In particular, when the defrost heater 330 is turned off and the post-defrost cooling mode pbdk is performed according to the opening of the cooling compartment door during the pulse operation mode Ponbk, the controller 310 of the refrigerator 100 may be configured to supply a predetermined level of cooling power. Here, the predetermined level may be cooling power corresponding to a maximum supplyable level Max. Accordingly, it may be possible to efficiently supply cooling power after defrosting.

FIG. 18C illustrates the same cooling power waveform Pcv as FIG. 9A.

Referring to the drawing, it is illustrated that an ON period of the defrost heater 330 is between Ta and Tc.

In this case, the ON period of the defrost heater 330 may include a continuous operation mode Pona and a pulse operation mode Ponb.

The controller 310 may determine a cooling power level in the post-defrost cooling mode Pbf based on the ON period of the defrost heater 330 in the pulse operation mode Ponb.

In the drawing, a cooling power of R+F level is supplied between Td and T4 in the post-defrost cooling mode pbf, and a cooling power of F level is supplied between T5 and T6 in the post-defrost cooling mode pbf.

FIG. 18D illustrates a different cooling power waveform Pcva than FIG. 18C.

Referring to the drawing, it is illustrated that an ON period of the defrost heater 330 is between Ta and Tea.

It can be seen that the ON period of the defrost heater 330 is further increased compared with the cooling power waveform Pcv of FIG. 18C. Accordingly, a period of the pulse operation mode of FIG. 18D is greater than that of the pulse operation mode of FIG. 18C.

The controller 310 may be configured to supply a cooling power of M level that is greater than the R+F level between Td and T4 in the post-defrost cooling mode pbf and supply a cooling power of F level between T5 and T6 in the post-defrost cooling mode pbf.

That is, the controller 310 may control the level of cooling power supplied in the post-defrost cooling mode pbf to increase as the ON period of the defrost heater 330 in the pulse operation mode Ponb increases. Accordingly, it may be possible to efficiently supply cooling power after defrosting.

FIG. 18E illustrates a different cooling power waveform Pcvb than FIG. 18D.

Referring to the drawing, it is illustrated that an ON period of the defrost heater 330 is between Ta and Tcb.

It can be seen that the ON period of the defrost heater 330 is further increased compared to the cooling power waveform Pcvb of FIG. 18D. Accordingly, the period of the pulse operation mode of FIG. 18E is greater than that of the pulse operation mode of FIG. 18D.

The controller 310 may be configured to supply a cooling power of M2 level that is greater than the M1 level between Td and T4 in the post-defrost cooling mode pbf, and supply a cooling power of F level between T5 and T6 in the post-defrost cooling mode pbf.

FIG. 19 is a flowchart illustrating a method defrosting and cooling after defrosting according to another embodiment of the present disclosure.

Referring to the drawing, the controller 310 of the refrigerator 100 according to an embodiment of the present disclosure determines whether a defrosting operation start time point has arrived for defrosting (S1610).

For example, the controller 310 of the refrigerator 100 may determine whether it is the defrosting operation start time point, while performing the normal cooling operation mode Pga. The defrosting operation start time point may vary according to a defrost cycle.

Meanwhile, when a defrosting operation start condition is satisfied, for example, in response to a defrosting operation start time point arriving, the controller 310 of the refrigerator 100 may end the normal cooling operation mode and control the defrost operation mode Pdf to be performed.

Meanwhile, the controller 310 of the refrigerator 100 may control the defrost heater 330 to be continuously turned on

based on the continuous operation mode Pona in the heater operation mode PddT of the defrost operation mode Pdf (S1615).

Next, the controller 310 of the refrigerator 100 may control the pulse operation mode to be performed after the continuous operation mode Pona (S1620).

For example, the controller 310 of the refrigerator 100 determines whether the temperature detected by the temperature sensor 320 reaches a reference temperature, and when the temperature detected by the temperature sensor 320 reaches the reference temperature, the controller determines whether an elapsed time until the reference temperature is reached is equal to or less than a reference time, and when the elapsed time until the reference temperature is reached is equal to or less than the reference time, the controller 310 of the refrigerator 100 controls to perform the pulse operation mode.

The controller 310 of the refrigerator 100 may control to perform the pulse operation mode based on the elapsed time until the reference temperature is reached.

Accordingly, the on and off of the defrost heater 330 may be repeated.

Next, the controller 310 of the refrigerator 100 determines whether the defrost end temperature has arrived (S1622), and when the defrost end temperature has arrived, the controller 310 of the refrigerator 100 ends the defrosting (S1624).

Accordingly, the controller 310 may turn off the defrost heater 330. Also, the controller 310 may control to perform post-defrost cooling.

Meanwhile, the controller 310 determines whether an ON period of the defrost heater 330 in the pulse operation mode Ponb or a temperature of the cooling compartment is less than or equal to a set value (S1645), and when the ON period of the defrost heater 330 in the pulse operation mode Ponb or the temperature of the cooling compartment is less than or equal to the set value, the controller 310 changes a magnitude of cooling power supplied in the post-defrost cooling mode pbf (S1650).

Meanwhile, when the ON period of the defrost heater 330 in the pulse operation mode Ponb or the temperature of the cooling compartment is not equal to or less than the set value, for example, when they exceed the set value, the controller controls so that maximum cooling power is output in the post-defrost cooling mode pbf (S1652). Accordingly, it may be possible to efficiently supply cooling power after defrosting.

Meanwhile, in response to the temperature of the cooling compartment being equal to or less than the cooling compartment reference temperature, the controller 310 may be configured to change the magnitude of cooling power supplied in the post-defrost cooling mode Pbf based on the ON period of the defrost heater 330 or the temperature of the cooling compartment, and in response to the temperature of the cooling compartment exceeding the cooling compartment reference temperature, the controller 310 may be configured to supply maximum cooling power in the post-defrost cooling mode Pbf. Accordingly, defrosting efficiency may be improved, power consumption may be improved, and cooling power after defrosting may be efficiently supplied.

Meanwhile, when the temperature of the refrigerating compartment is equal to or lower than the refrigerating compartment reference temperature refmb and the temperature of the freezer compartment is equal to or lower than the freezer compartment reference temperature refma, that is, when it corresponds to the Arma region of FIG. 13A, the

controller 310 may be configured to change the magnitude of cooling power supplied in the post-defrost cooling mode pbf based on the ON period of the defrost heater 330 or the temperature of the cooling compartment. Accordingly, it may be possible to efficiently supply cooling power after defrosting.

Meanwhile, in response to the temperature of the refrigerating compartment exceeding the refrigerating compartment reference temperature refmb and the freezer compartment temperature exceeding the freezer compartment reference temperature refma, that is, when it corresponds to the armb region of FIG. 13A, the controller 310 may be configured to supply maximum cooling power in the post-defrost cooling mode pbf. Accordingly, it may be possible to efficiently supply cooling power after defrosting.

Meanwhile, in the post-defrost cooling mode pbf, the controller 310 of the refrigerator 100 may determine whether a cooling power varying release condition is satisfied while the cooling power changes (S1655), and when cooling power variable release condition is satisfied, the controller 310 of the refrigerator 100 may be configured to supply a predetermined level of cooling power (S1660). In this case, the predetermined level may correspond to a maximum level.

For example, in response to the cooling compartment door being opened in the post-defrost cooling mode pbf, the controller 310 of the refrigerator 100 may stop varying the cooling power and control so that the maximum level of cooling power is supplied.

As another example, in the post-defrost cooling mode pbf, when an internal temperature of the cooling compartment is higher than or equal to an allowable temperature higher than a target temperature, the controller 310 of the refrigerator 100 may stop varying the cooling power and control so that the maximum level of cooling power is supplied. Accordingly, it may be possible to quickly control the internal temperature to reach the target temperature during cooling.

FIG. 20 is a flowchart illustrating a method of defrosting and cooling after defrosting according to another embodiment of the present disclosure.

Referring to the drawing, the controller 310 of the refrigerator 100 determines whether a defrosting operation start time point arrives for defrosting (S1610).

For example, the controller 310 of the refrigerator 100 may determine whether it is the defrosting operation start time point, while performing the normal cooling operation mode Pga. The defrosting operation start time point may vary according to a defrost cycle.

Meanwhile, when a defrosting operation start condition is satisfied, for example, in response to a defrosting operation start time point arriving, the controller 310 of the refrigerator 100 may end the normal cooling operation mode and control to perform the defrost operation mode Pdf.

Meanwhile, the controller 310 of the refrigerator 100 may control the defrost heater 330 to be continuously turned on based on the continuous operation mode Pona in the heater operation mode PddT of the defrost operation mode Pdf (S1615).

Next, the controller 310 of the refrigerator 100 may control the defrost heater 330 to be repeatedly turned on and off based on the pulse operation mode Ponb after the continuous operation mode Pona (S1620). Accordingly, it may be possible to improve the defrost efficiency and improve the power consumption.

Next, the controller 310 of the refrigerator 100 determines whether a pulse operation mode end time point has arrived

(S1630), and if pulse operation mode end time point has arrived, the controller 310 turns off the defrost heater 330 (S1640).

For example, the pulse operation mode end time point may be a time point at which the temperature detected by the temperature sensor 320 falls below a phase-change temperature Trfl.

As another example, the pulse operation mode end time point may be an end time point of the defrosting operation or an end time point of the heater operation mode.

Meanwhile, the controller 310 of the refrigerator 100 may control to end the heater operation mode PddT after the defrost heater 330 is turned off and to perform the post-defrost cooling mode Pbf.

Next, the controller 310 of the refrigerator 100 determines whether the cooling compartment temperature in the previous defrosting operation has arrived at a target temperature (S1643), and when the cooling compartment temperature in the previous defrosting operation has not reached a target temperature, the controller 310 of the refrigerator 100 may control to supply a predetermined level of cooling power in the post-defrost cooling mode pbf (S1663). The controller 310 of the refrigerator 100 may control to supply a maximum level of cooling power.

In consideration of the increase in the cooling compartment temperature in the previous defrosting operation, the maximum cooling power may be supplied in the post-defrost cooling mode Pbf in the currently performed defrost operation mode, so that the target temperature may be reached.

Meanwhile, when the cooling compartment temperature in the previous defrosting operation reaches the target temperature, the controller 310 of the refrigerator 100 determines whether a defrosting end temperature in the previous defrosting operation is equal to or higher than a set temperature (S1646), and when the defrosting end temperature in the previous defrosting operation is equal to or higher than the set temperature, the controller 310 of the refrigerator 100 may control to supply a predetermined level of cooling power (S1663). The controller 310 of the refrigerator 100 may control to supply the maximum level of cooling power.

In consideration of the increase in the cooling compartment temperature in the previous defrosting operation, the maximum cooling power is supplied in the post-defrost cooling mode Pbf in the currently performed defrost operation mode, so that the target temperature may be reached.

Meanwhile, in steps 1643 and 1646, when the target temperature is reached and the temperature is less than the set temperature, step 1650 may be performed.

Next, the controller 310 of the refrigerator 100 controls the magnitude of cooling power supplied in the post-defrost cooling mode Pbf to be varied based on the ON period of the defrost heater 330 in the pulse operation mode Ponb or the temperature of the cooling compartment (S1650).

Accordingly, it may be possible to improve defrosting efficiency, improve power consumption, and efficiently supply cooling power after defrosting.

The refrigerator according to the present disclosure is not limited to the configurations and the method of the embodiments described above, but the embodiments may be configured by selectively combining all or part of each embodiment so that various modifications can be made.

While the present disclosure has been particularly shown and described with reference to preferred embodiments thereof, it will be understood by those skilled in the art that the present disclosure is not limited to those exemplary

embodiments and various changes in form and details may be made therein without departing from the scope and spirit of the invention.

The present disclosure may be applied to a refrigerator, and more particularly, may be applied to a refrigerator capable of improving defrosting efficiency and power consumption.

What is claimed is:

1. A refrigerator comprising:
an evaporator configured to perform heat exchange;
a defrost heater configured to operate to remove frost from the evaporator;
a temperature sensor configured to detect an ambient temperature of the evaporator; and
a controller configured to control the defrost heater, wherein, in response to a defrosting operation start time point arriving, the controller is configured to perform a defrost operation mode including a pre-defrost cooling mode, a heater operation mode, and post-defrost cooling mode, perform a pulse operation mode in which the defrost heater is repeatedly turned on and off based on the heater operation mode, and change a magnitude of cooling power supplied in the post-defrost cooling mode based on an ON period of the defrost heater or a temperature of a cooling compartment in the pulse operation mode,
wherein the pre-defrost cooling mode includes:
a first period in which cooling power of a first level is supplied,
a second period in which cooling power of a second level higher than the first level is supplied,
a third period in which cooling power is not supplied,
a fourth period in which cooling power of the first level is supplied,
wherein the fourth period is shorter than the first period, and the heater operation mode is performed after the fourth period,
wherein the magnitude of the cooling power supplied in the post-defrost cooling mode is greater than the second level in the pre-defrost cooling mode.
2. The refrigerator of claim 1, wherein, in response to the ON period of the defrost heater or the temperature of the cooling compartment in the pulse operation mode being less than or equal to a set value, the controller is configured to change the magnitude of cooling power supplied in the post-defrost cooling mode based on the ON period of the defrost heater or the temperature of the cooling compartment, and in response to the ON period of the defrost heater or the temperature of the cooling compartment in the pulse operation mode exceeding the set value, the controller is configured to supply maximum cooling power in the post-defrost cooling mode.
3. The refrigerator of claim 1, wherein in response to the temperature of the cooling compartment being equal to or lower than a cooling compartment reference temperature, the controller is configured to change the magnitude of cooling power supplied in the post-defrost cooling mode based on the ON period of the defrost heater or the temperature of the cooling compartment, and in response to the temperature of the cooling compartment exceeding the cooling compartment reference temperature, the controller is configured to supply maximum cooling power in the post-defrost cooling mode.

4. The refrigerator of claim 1, wherein in response to a temperature of a refrigerating compartment being equal to or lower than a refrigerating compartment reference temperature and a temperature of a freezer compartment is equal to or lower than a freezer compartment reference temperature, the controller is configured to change the magnitude of cooling power supplied in the post-defrost cooling mode based on the ON period of the defrost heater or the temperature of the cooling compartment, and

in response to the temperature of the refrigerating compartment exceeding the refrigerating compartment reference temperature and the temperature of the freezer compartment exceeds the freezer compartment reference temperature, the controller is configured to supply maximum cooling power in the post-defrost cooling mode.

5. The refrigerator of claim 1, wherein, as the ON period of the defrost heater in the pulse operation mode increases or as the temperature of the cooling compartment, which is equal to or lower than the cooling compartment reference temperature, increases, the controller is configured to increase the magnitude of cooling power supplied in the post-defrost cooling mode.

6. The refrigerator of claim 1, wherein the controller is configured to change a magnitude of cooling power supplied in the post-defrost cooling mode in inverse proportion to a difference between the set temperature and the temperature of the cooling compartment, after the pulse operation mode.

7. The refrigerator of claim 1, wherein, in response to the continuous operation mode being performed after the pulse operation mode or in response to the pulse operation mode being performed after the continuous operation mode, the controller is configured to control the magnitude of cooling power supplied in the post-defrost cooling mode to be larger than in response to only the pulse operation mode being performed.

8. The refrigerator of claim 1, wherein the controller is configured to change the magnitude of cooling power supplied in the post-defrost cooling mode in proportion to a door opening period during the pulse operation mode.

9. The refrigerator of claim 1, wherein in response to the defrosting operation start time point arriving while performing the normal cooling operation mode, the controller is configured to perform the defrost operation mode including the pre-defrost cooling mode, the heater operation mode, and the post-defrost cooling mode, and perform the continuous operation mode of the defrost heater and the pulse operation mode in which the defrost heater is repeatedly turned on and off based on the heater operation mode.

10. The refrigerator of claim 1, wherein the controller is configured to continuously turn on the defrost heater based on the continuous operation mode, and

in response to a change rate of an ambient temperature of the evaporator detected by the temperature sensor being equal to or greater than a first reference value in the ON state of the defrost heater, the controller is configured to enter the pulse operation mode and turn off the defrost heater, and in response to the change rate of the ambient temperature of the evaporator being less than

39

or equal to a second reference value less than the first reference value in the OFF state of the defrost heater during the pulse operation mode, the controller is configured to turn on the defrost heater.

11. The refrigerator of claim 1, wherein the controller is configured to continuously turn on the defrost heater based on the continuous operation mode, and repeatedly turn on and off of the defrost heater for the change rate of the ambient temperature of the evaporator to be between a first reference value and a second reference value based on the pulse operation mode.

12. The refrigerator of claim 1, wherein as the number of opening times of the cooling compartment door increases, the controller is configured to decrease a period of performing the defrost operation mode.

13. The refrigerator of claim 1, wherein the controller is configured to control a peak temperature arrival point of the evaporator in response to the continuous operation mode and the pulse operation mode being performed in the defrost operation mode to be later than a peak temperature arrival point of the evaporator in response to the defrost heater being only continuously turned on in the defrost operation mode.

14. The refrigerator of claim 1, wherein the controller is configured to control an effective defrost in response to the continuous operation mode and the pulse operation mode being performed in the defrost operation mode to be greater than an effective defrost in response to the defrost heater being only continuously turned on in the defrost operation mode.

15. The refrigerator of claim 1, wherein the controller is configured to control a heater OFF time point in response to the continuous operation mode and the pulse operation mode being performed in the defrost operation mode to be later than a heater OFF time point in response to the defrost heater being only continuously turned on in the defrost operation mode.

16. The refrigerator of claim 1, wherein the controller is configured to perform the continuous operation mode in which the defrost heater is continuously turned on and perform the pulse operation mode in which the defrost heater is repeatedly turned on and off based on the heater operation mode, and in response to the cooling compartment door being opened during the continuous operation mode, the controller is configured to turn off the defrost heater, and supply a predetermined level of cooling power in the post-defrost cooling mode.

17. A refrigerator comprising:
an evaporator configured to perform heat exchange;
a defrost heater configured to operate to remove frost from the evaporator;
a temperature sensor configured to detect an ambient temperature of the evaporator; and
a controller configured to control the defrost heater, wherein, in response to a defrosting operation start time point arriving, the controller is configured to perform a defrost operation mode including a pre-defrost cooling mode, a heater operation mode, and post-defrost cooling mode, and perform a continuous operation mode in which the defrost heater is continuously turned on and a pulse operation mode in which the defrost heater is repeatedly turned on and off based on the heater operation mode, and

40

in response to a cooling compartment door being opened during the continuous operation mode, turn off the defrost heater and supply predetermined level of cooling power in the post-defrost cooling mode,

wherein the pre-defrost cooling mode includes:
a first period in which cooling power of a first level is supplied,
a second period in which cooling power of a second level higher than the first level is supplied,
a third period in which cooling power is not supplied,
a fourth period in which cooling power of the first level is supplied,

wherein the fourth period is shorter than the first period, and the heater operation mode is performed after the fourth period,

wherein the magnitude of the cooling power supplied in the post-defrost cooling mode is greater than the second level in the pre-defrost cooling mode.

18. The refrigerator of claim 17, wherein, in response to the cooling compartment door being opened during the continuous operation mode, the controller is configured to end the continuous operation mode, turn off the defrost heater, and supply a predetermined level of cooling power in the post-defrost cooling mode.

19. The refrigerator of claim 17, wherein, in response to the cooling compartment door being opened during the pulse operation mode, the controller is configured to end the pulse operation mode, turn off the defrost heater, and supply a predetermined level of cooling power in the post-defrost cooling mode.

20. A refrigerator comprising:
an evaporator configured to perform heat exchange;
a defrost heater configured to operate to remove frost from the evaporator;
a temperature sensor configured to detect an ambient temperature of the evaporator; and
a controller configured to control the defrost heater, wherein, in response to a defrosting operation start time point arriving, the controller is configured to perform a defrost operation mode including a pre-defrost cooling mode, a heater operation mode, and post-defrost cooling mode,

perform a continuous operation mode in which the defrost heater is continuously turned on and a pulse operation mode in which the defrost heater is repeatedly turned on and off based on the heater operation mode, and change a magnitude of cooling power supplied in the post-defrost cooling mode based on an ON period of the defrost heater or a temperature of the cooling compartment in the pulse operation mode, and

in response to the temperature of the cooling compartment in a previous defrost operation not reaching a target temperature or in response to a defrost end temperature in the previous defrost operation being equal to or higher than a set temperature, the controller is configured to supply a predetermined level of cooling power in the post-defrost cooling mode,

wherein the pre-defrost cooling mode includes:
a first period in which cooling power of a first level is supplied,
a second period in which cooling power of a second level higher than the first level is supplied,
a third period in which cooling power is not supplied,
a fourth period in which cooling power of the first level is supplied,

wherein the fourth period is shorter than the first period,
and the heater operation mode is performed after the
fourth period,

wherein the magnitude of the cooling power supplied in
the post-defrost cooling mode is greater than the second 5
level in the pre-defrost cooling mode.

* * * * *
